UNITED STATES PATENT OFFICE

2,288,823

STATISTICAL MACHINE

Joseph M. McDonnell, Ozone Park, N. Y., assignor
to Remington Rand Inc., Buffalo, N. Y., a corporation of Delaware

Application May 28, 1938, Serial No. 210,688

4 Claims. (Cl. 235—61.7)

This invention relates generally to punched card accounting machines adapted to list a set of serially numbered sequentially arranged record cards according to the consecutively numbered groups of cards contained therein, and more particularly to a machine of this type which includes grand total mechanism of a modified form provided to permit the accuracy of the listing to be proved in a rapid and simple manner, and an item receiving device adapted to control the printing of the last number of each consecutively numbered group of cards.

The machine of the present invention is a modification of the standard Powers tabulator and constitutes an improvement upon the machine of my Patent No. 2,280,924, issued April 28, 1942, which machine lists the cards according to their consecutively numbered groups but is not provided with the grand total mechanism disclosed herein. Although the taking of grand totals in the usual tabulating machines is an old and well known function, the installation of such mechanism on a machine of the type disclosed in Patent No. 2,280,924 requires considerable modification of the accumulator control mechanism and the addition of certain new mechanism to effect the transferring of totals from one accumulator to another. Included in the mechanism of the invention is a set of storage sectors of novel construction and operation utilized herein to control the printing of the last number of a consecutively numbered group. These sectors constitute an item receiving device into which the serial number of each successive record card is entered during a portion of one cycle and is then cancelled therefrom during a different portion of the next succeeding cycle. A break in the consecutive order of the serial numbers causes a total taking operation resulting in a brief disabling of the cancelling means during which time the number then represented on the sectors, which number is the last of a consecutive group, is withdrawn from the sectors and printed. Apart from the modified total taking mechanism and the above storage sectors the machine of the present application and that of Patent No. 2,280,924 are the same in construction, operation and function. The function of the present machine, generally stated, is to compare the serial number of each successive record card with that of its immediate predecessor, to perform a total taking operation automatically upon a break in the consecutive order of the serial numbers, and to print, upon a single line of the report sheet, the first number of a

consecutively numbered group, the last number of the group and the total number of cards in the group; all suitably spaced apart so as to be easily distinguishable. Printing is effected only during total taking operations. As this group listing continues throughout a run of cards these "first numbers," "last numbers" and "total numbers" are entered into separate portions of a single accumulator unit and at the end of the tabulation of a set of cards this accumulator is cleared (by means of a special card) and the amounts therein printed to obtain a grand total of all the first numbers, a grand total of all the last numbers and the card count signifying the total number of cards in the completed set. The purpose of obtaining these three grand totals is, as was mentioned above, to permit the accuracy of the listing just completed to be proved thereby providing a definite check against misoperation of the machine. This proving requires a slight mental calculation on the part of the operator with respect to these three totals. This mental calculation lies in subtracting the total of the "first numbers" from the total of the "last numbers" and then subtracting the difference thus obtained from the third or card count total. If the listing is correct this final difference will be the same number as the number of consecutive groups listed. This method of proving the listing is based upon mathematical fact and there is included in the accompanying drawings a short example of a listing and the manner of proving it.

It will thus be seen that the present invention resides in a modification of the machine of Patent No. 2,280,924 whereby grand total mechanism is adapted for use in a machine of that type and item receiving mechanism is provided for controlling the printing of the last number of each consecutively numbered group of cards passed through the machine.

One object of this invention is to make possible a simple manner of providing the correctness of the listing produced by a machine of the type disclosed in Patent No. 2,280,924 through the installation of grand total mechanism therein.

Another object of the invention is to control the printing of the last number of a consecutively numbered group of cards from special storing mechanism adapted to retain only one number at a time.

Another object of the invention is to provide suitable accumulator control mechanism for transferring totals and single numbers from one accumulator to another.

Other objects and structural details of the invention will be apparent from the following description when read in connection with the accompanying drawings, wherein:

Fig. 38 is a view of a segment of a report sheet illustrating the manner in which the serial numbers are listed and the listing proved; and

Fig. 39 is a detailed plan view of the rear accumulator unit.

MACHINE OPERATION

As previously mentioned, the machine of the present application is a modification of the well known Powers tabulator and is similar in its general features of construction and operation to the machine described in the above Patent No. 2,280,924. With the exception of certain alterations in the timing and the total control mechanism to be described later, the mechanism for feeding and analyzing the record cards is the same as that disclosed in the patent to William W. Lasker No. 2,044,119 issued June 16, 1936. As disclosed in the above patent, and illustrated herein, the machine is power driven by an electric motor (not shown) and suitable gearing, including a worm gear 1 (Fig. 1), leading directly from the motor is employed to drive a main base shaft 2 (Figs. 1 and 2) and a main head shaft 3 (Figs. 3 and 4). The mechanism of the base is mounted on a base plate 4 (Figs. 1 and 2) and is enclosed by frame plates 5 also mounted on the base plate 4. Intermediate frame plates 6 (Fig. 5) are fastened, at their lower ends, to the base frames 5 and are secured, at their upper ends, to another plate 7 (Figs. 3 and 4) on the upper surface of which the various head mechanisms are mounted. Additional framework 8 (Fig. 4), which contributes to the support of the head mechanism, is mounted on the base plate 7 and the entire head section (except, of course, the printing platen) is enclosed by light metal easily removable casings (not shown).

Mechanism not fully shown herein but which has been disclosed in numerous previous applications and patents is provided for switching the electric motor on and off, and for causing the engagement and disengagement of the worm gear 1 with the drive controlled by the motor. The Lasker Patent 2,044,119 is again referred to for a more complete disclosure of the above clutch mechanism and for all other base mechanisms not herein specifically indicated.

CARD FEED AND SENSING

Referring now to Figs. 2 and 5, the storage chamber or card magazine is shown therein, indicated by the reference numeral 9. A stack

of perforated record cards is adapted to be placed in the magazine 9 and a picker knife and block 11 is provided to feed the cards seriatim from the magazine into position for sensing. The picker knife 11 is reciprocated through the base of the card magazine once for every cycle of the shaft 2, by a link 12 connected to the block, an arm 13 connected at one end to the link 12 and at its other end fast to a shaft 14, and a cam secured on the main shaft 2. This construction is shown in Figs. 7 and 8 and includes a cam 2a fixed on shaft 2 and cooperating with a roller 2b on arm 2c fixed on stub shaft 2d journaled on the machine base frame in any suitable manner. A link 14c is at one end connected to arm 2c and at the other end connected to arm 14a fixed to shaft 14. The arm 14a is urged in a predetermined direction by a spring 14b. Each of the cards is fed between a pair of power driven feed rolls 15 and thereby into the sensing chamber comprised of a pair of perforated plates 16 and 17. As the card enters the sensing chamber it is picked up by a pair of spring tensioned rollers (not shown) and driven rearwardly until it comes to rest against a card stop 18. The card stop 18 is reciprocated vertically by a cam on the main shaft 2 once for every cycle of the machine to block the exit of the sensing chamber while the card is being sensed. The card stop mechanism used in the present machine is identical with that disclosed in the abovementioned patent and need not be further described here. The sensing of the card is performed by a plurality of pins 19 supported in a pin box 21. The pin box 21 is reciprocated vertically once for each cycle of the machine by an eccentric disk 22 mounted on the shaft 2. There are forty-five columns of pins 19 and each column consists of twelve pins. Therefore an entire card, whether it be of a forty-five or ninety-column type may be sensed in one operation. Returning now to the card locked in the sensing chamber it will be seen that the rising pins 19 will pass through their respective perforations in the lower chamber plate 17. Those pins 19 which find perforations in the card will continue to rise, passing through the card and into the upper chamber plate 16. Those pins which find no perforation merely press idly against the bottom of the card while the pin box continues to rise against the tension of springs 23, one of which is provided for each pin 19. A locking slide 24 is provided to engage the elevated pins 19 and impart to them a positive elevating movement. Positioned directly above the sensing pin box 21 is an intermediate pin box 25 (Fig. 5) which supports intermediate pins 26 in equal number and arrangement to the sensing pins 19. The lower ends of the pins 26 lie directly over their respective pins 19 so that any positively elevated pin 19 will contact and elevate its associated pin 26 against the tension of springs 27, one of which surrounds each of the intermediate pins. Each of the pins 26 is provided with lateral extrusions 28 adapted to cooperate with a spring urged locking slide 29. Six of the pins 26 in each column have their extrusion 28 pointing in one direction while the other six pins have their extrusions pointing in the opposite direction. Each set of six extrusions 28 is adapted to cooperate with a separate locking slide 29 so that either set of six pins 26 may be operated independently of the other set. As is well known in this type of machine the above arrangement of locking slides is used only in the ninety-column

machines. In a forty-five-column machine such as that disclosed in the Lasker Patent 2,044,119 all twelve of the extrusions 28 extend in the same direction and only one locking slide 29 is used, per column. The function of the locking slides 29 is to lock all of the elevated pins 26 and retain them in elevated position until the reading which they convey to the computing mechanism has been accumulated and printed. 5 The slides 29 are retracted once for each cycle of the machine to release the elevated pins 26 by a bail 31 supported at the rear of the slides 29 by a pair of arms 32 secured to a shaft 33. The shaft 33 is adapted to be moved in a reciprocal rocking motion by a cam on the main shaft 2. The retraction of the slides 29 is a short spasmodic operation and occurs at a time when the sensing pins 19 are in their highest elevated position so that if identical designation matter appears on two successive cards, the originally elevated pins 26 will not be permitted to descend. A second pair of slides 34 is associated with each column of pins 26 and is operated by extrusions 35 in the same manner as slides 29. The slides 34, however, are not locking slides, but may be called total trip or change of designation slides since their only function is to sense a change in the designating number on a card and to institute a total taking operation 10 when such a change occurs.

TRANSLATOR

The numerical values represented by the upraised pins 26 are transmitted to the head section of the machine, and to the card counting and comparing mechanisms by means of the usual translator 36 (see Figs. 5 and 6) in which is supported a plurality of translator wires 37. In place of the customary rigid type of translator wire, the present machine makes use of the more flexible Bowden wire, thereby requiring the provision of interponent pins between the pins 26 and the translator wires themselves. In the majority of the Powers tabulators the translator is an independent self contained unit which may be easily removed and replaced with a translator of different wiring according to the exigencies of the accounting work to be done. Provision is also made in each translator for accommodating one wire 37 for each pin 26. In the present machine however only a small portion of the card is used at one time so that only as many wires as are necessary to the operation of this machine are mounted in the translator now to be described.

The machine of the Patent No. 2,280,924 was described as operating on record cards bearing serial numbers of six digits or less and for purposes of description the same number is used herein. It should be understood, however, that this number is merely selected by way of a specific example and that the machine may be constructed to accommodate a serial number of any number of digits. Each record card, therefore, bears a serial number of six digits or less and in addition to this bears a special control hole for a purpose later to be explained. Referring now to Fig. 6, each of the translator wires 37 associated with these columns in which the serial number appears, ends in a connector 38 from each of which extends three individual wires 37A, 37B, and 37C. The wire 37A, as shown, extends into a unit designated in Fig. 6 as "first number." The wire 37B extends into the unit designated "last number" and the wire 37C into

the rear of a pin box secured to the right-hand side of the translator. This pin box is associated with the card comparing mechanism and will be considered in greater detail a little later in the description. The special control hole, previously mentioned, is adapted to control a separate translator wire 37 which also ends in a connector 38A. Extending from the connector 38A is a wire 41, which extends into the unit marked "total," and a wire 42 which also extends into the pin box on the front of the translator to serve a purpose later to be described. The elevation of any wire 37, therefore, will cause the simultaneous operation of the wires 37A, 37B, and 37C associated with the elevated wire 37. When the machine is used for counting and comparing work each card will bear a special control hole so that the special wires 41 and 42 will be in constant operation. The use of Y wires in the translator to transmit identical data simultaneously into a plurality of accumulating units is old and well known in the Powers machine so that a further discussion of the arrangement of this translator seems unnecessary. These three units, marked "first No." "last No." and "total" are actually separate portions of one large unit and coact in a manner, soon to be described, with a single twenty-five place printing and accumulating unit. The Bowden wires in the translator operate pins 50 in the well known manner to set up the stops in the stop basket.

STOP BASKET

The above units "first number," "last number," and "total" are associated in the usual manner with a regular twenty-five place Powers type stop basket mounted in a frame or tray 46 (see Fig. 3) supported between the side frames 8 of the head. Contained in the basket are twenty-five columns of digit stops 47 which are adapted to limit the movement of the usual actuating sectors 48, one of which is provided for each column of stops 47. In a ninety-column machine, such as the one now under discussion, each column of digit stops 47 is formed of five independently movable stops or bars and a normally ineffective zero stop 49. The manner in which the digit stops 47 operate to limit the movement of the sectors 48 and thereby position type sectors 51, connected to the sectors 48, is too well known to require further discussion here. Each of the zero stops 49 is individually and resiliently connected to a bellcrank 52 loosely mounted on a shaft 53 supported between the side frames of the stop basket. Each bellcrank lever 52 is tensioned, by means of a spring 54, to move in a clockwise direction to hold elevated its respective stop 49. As shown in Fig. 3, however, all of the levers 52 in the entire unit are normally held rocked against the tension of their springs 54 by a bail 55 supported between a pair of arms 56 (one shown) on a rock shaft 57. The assembly comprising arms 56 and bail rod 55 is loosely pivoted on the shaft 57 and may be operated either by a pair of operating fingers 43 (one shown) fast on the shaft 57 or through another means, later to be described, independently of the shaft. The shaft 57 is rocked at the end of each machine cycle so that the zero stops 49 are normally held depressed. As shown in Fig. 36, there is secured to the left-hand end of the shaft 57, outside the frame piece 8, an arm 500 bearing a roller adapted to follow the periphery of a cam 591 fast on the left-hand end of the drive shaft 3 of the head. The cam 591 is nor-

mally positioned as shown to hold the shaft 57 rocked, but it will be seen that, shortly after the shaft 3 begins to rotate (clockwise as viewed in Fig. 36), the arm 500 and its shaft 57 will follow a short distance, thereby permitting the zero stops 49 to rise into effective engaging position. In those columns, however, in which a digit stop 47 is raised, a slide 58 (Fig. 3) (one of which is associated with each column of digit stops) is cammed to the right to hold the zero stop associated with that particular column depressed. During total strokes the shaft 57 is held rocked (by means later to be described) to disable all of the zero stops 49 for the duration of the total cycle.

PRINTING MECHANISM

The actuating sectors 48 and the printing sectors 51, associated with the above stop basket are pivoted to a common shaft 59 (Fig. 3) journaled between the side frames 8. A spring 61, tensioned between a rear extension of each type sector 51 and a spring anchor 62 tends to swing the type sectors 51 and their associated actuating sectors upward in a clockwise direction (Fig. 3) about the shaft 59. The sectors, however, are constrained to follow the movements of a bail rod 63 which is supported between the lower ends of a pair of arms 64 (one shown) pivoted on the shaft 59. The bail 63 normally holds the sectors 48 and 51 retracted against the tension of springs 61 and it is moved forwardly once for each cycle of the shaft 3 to permit all of the sectors 51 which are not retained by zero stops 49 to follow and position their type elements 65 to effect printing against the platen 66. On the return stroke of bail 63 all of the sectors 48 and 51 are picked up and restored to normal against the tension of springs 61. The type elements 65 are struck by hammers 67 released and operated in a manner well known in this type of machine. Certain actuating mechanism for operating the restoring bail 63 and for releasing the hammers 67 is shown in Figs. 3 and 4, driven from the main head shaft 3. Referring to Fig. 4 a cam 68 is secured to the right-hand end of the shaft 3 and a pitman 69 is pivotally connected, at one end, to the outside surface of the cam 68 and at its other end to one arm 71 of a bell-crank lever secured to a shaft 72. The shaft 72 is loosely mounted between the side frames 8 and it is evident that rotation of shaft 3 will impart a reciprocable rocking motion to the shaft 72, once for each cycle of the shaft 3, through pitman 69. The driving mechanism shown herein is the same as that used in the usual Powers machines and comprises generally a slotted lever 73 (Fig. 3), secured to the shaft 72, and to which is connected a long forwardly extending link 74 connected to one of the arms 64, and also, by means of the resilient extension 75 to an arm (not shown) on a shaft 77 of the hammer release mechanism. During the first 180° of rotation of the shaft 3, the shaft 72 is rocked in a clockwise direction (Fig. 3) and the link 74 is driven forwardly to rock the bail 63 upwardly and to rock the shaft 77 in a clockwise direction, thus releasing the printing hammers 67. During the second 180° of rotation of the shaft 3, the shaft 72 is rocked in a counter-clockwise direction, thus permitting a heavy spring 74A (Fig. 3) to return the operating link 74, thereby restoring the bail 63 and the shaft 77 both to normal. The reciprocation of shaft 72 occurs once for each machine cycle, but, as previously explained, the release of the

type sectors is contingent upon the elevation of the digit stops 47 or the operation of the total taking mechanism. If all of the type sectors are held in the zero position, none of the printing hammers 67 will be released since the printing hammers must be conditioned for operation by a moving type sector, as is well known in this type of machine. The type sectors 51 are normally positioned with their first or zero element positioned just below the printing line, which is their full carry position as is well known in the art. As will be later described, printing is effected in the present machine only during total cycles.

ACCUMULATING MECHANISM

The accumulating mechanism used in the present machine is, generally, of the same type that has long been used in the Powers type tabulator. In the regular tabulating machine equipped to take both totals and grand totals, there are provided two separate accumulators for each printing unit of the machine. One accumulator is positioned near the front of the machine and is actuated by the reciprocal sectors 48 (Fig. 3) while the second accumulator is positioned near the rear of the machine and is actuated by a set of auxiliary racks connected to the type carriers 51. Now, considering further the regular accumulating mechanism, both the front and rear accumulators are caused to engage their respective racks during the second half of each adding and listing cycle to receive the item just printed. These accumulators are so controlled during total taking operations as to enable the regular group total to be taken from the rear accumulator and the grand total of all the groups to be taken from the front accumulator. While a total is being taken from one accumulator, the other one is held from engagement with its racks.

To obtain the function of the present machine of listing the first and last numbers of a consecutively numbered group, it is evident that the standard type accumulating mechanism, outlined above, could not be used herein without considerable modification both as to its arrangement and its controls. Stated in general terms, the accumulating mechanism of this machine is arranged, and operates, in the following manner. For the front accumulator there is provided, in place of the usual ten place unit, a large 25 wheel accumulator, operable in the usual manner by the sectors 48. The rear accumulating mechanism is also comprised in one large unit, but is split up into three smaller units or sections, each of which is associated with a respective portion of the front accumulator. Two of these sections ("first No." and "total") operate together, under a common control, and function as standard accumulating units. The third section is positioned between the above two sections and operates under separate controls to yield the last number of each consecutively numbered group. This middle unit or section is not actually an accumulating unit at all in the true sense of the word, but is rather a storage device wherein each successive serial number is entered during one cycle and cancelled in the next until a break in the consecutive order occurs. The construction and operation of this rear unit comprising these "first No.," "last No.," and "total No." sections will be entered into in greater detail at a point later in the description. For the moment it may be merely said that the computing or accumulating mechanism of the machine consists of a

single front accumulator, one portion of which is set aside for the accumulation of "first Nos."—a second portion for the accumulation of "last Nos."—and a third portion for the accumulation of the total number of cards in each group—; and that the accumulating mechanism further consists of a rear accumulator unit divided into three sections, two of which are associated with the respective "first No." and "total No." portions of the front accumulator and the third of which acts as a special storage device to obtain the "last No." of each group, and cooperates with the associated "last No." portion of the front accumulator. The rear accumulators are used to obtain each individual group listing and are cleared upon each total cycle. The front accumulator is used to obtain separate grand totals of all the first numbers, the last numbers and the total numbers. This is done by holding the front accumulator normally disengaged and by effecting a transfer, during total cycles, from the rear accumulators to the front.

In the operation of the machine, it will be recalled that, through the medium of the Y wires 37A and 37B, each successive serial number is set up simultaneously in both the "first No." and "last No." portions of the stop basket. Control mechanism, later to be described, is provided for the "first No." unit which enables the first number of a consecutive order to be entered into the rear accumulator associated with this unit and which then acts to block the movement of the six sectors comprising this unit during all subsequent cycles until a total taking operation occurs. Thus, although the stops 47 are set up in this portion of the unit upon each accumulating cycle of the machine, the associated group of sectors 48 and 51 are permitted to move only during total taking cycles and the cycle immediately following a total. In the "last No." portion of the unit, the six sectors comprising this unit are free to be positioned in the usual manner; the storage device previously mentioned being provided to obtain the "last No." The "total" number portion of the unit is in effect a true total and grand total unit. The special translator wire 41 is arranged to elevate the number "one" digit stop in the lowest order column of the "total" unit, so that each time a card is sensed, the special wire 41 is elevated and a "one" is counted into the rear accumulator associated with this unit. Thus, a total is obtained in this accumulator of the number of cards in each consecutive order. As previously mentioned, a total-taking operation is initiated automatically upon a break in a consecutive order (through means later to be described), and during a total taking operation the "first No." of the sequence just broken, the "last No." and the "total" indicating the total number of cards in the group, are all printed and during the same machine cycle are entered into their respective portion of the front grand total accumulator. A special control card may be used to clear the grand total accumulator as is well known in this type of machine.

ACCUMULATOR CONTROL—Front

Consider now the accumulator control mechanism in detail. As shown in Fig. 3, the front or grand total accumulator is comprised of twenty-five accumulator wheels 78 and their associated carry mechanism. The wheels 78 are loosely mounted on a common shaft 79 supported at its opposite ends by a pair of swinging arms 81 (one

shown) pivoted to a fixed frame piece 82. The shaft 79 is further supported and guided by a movable slotted cam arm 83 fixed on a shaft 84, and adapted to engage the left-hand end of the shaft 79. Connected to the cam arm 83 is a forwardly extending link 85 formed with two oppositely arranged notches 85A and 85B cut respectively in the upper and lower edges of the link near its forward end. The notches 85A and 85B are adapted to be variably engaged by respective pins 86A and 86B integral with a lever 86, fast to the left-hand end of a stub shaft 87 loosely supported by certain frame pieces. The shaft is adapted to be moved in a reciprocable rocking motion once for each cycle of the machine through an arm 88 fast on the right-hand end of the shaft, a link 89 connected to the arm 88, and a lever 90 connected to the link 89 and secured to an accumulator rock shaft 92. As shown in Fig. 4 the rock shaft 92 is journaled between brackets mounted on the plate 7 and is operated from the previously mentioned cam 68, through a follower arm 93 operable directly by the cam, and a link 94 connecting the arm 93 and another arm 95 fast on the right-hand end of the shaft 92. The follower arm 93 is urged into contact with its cam 68 by means of a heavy spring 90 and from the contour of the cam it will be seen that, through the above linkage the shaft 92, will move first in a counter-clockwise direction, and then clockwise in a reciprocable rocking motion once for each machine cycle. The shaft 87 (Fig. 3), operable from the shaft 92, will also be rocked as a result of this operation, but will move in a direction opposite to the shaft 92. That is, during the first half or forward stroke of the shaft 92, the shaft 87 will rock in a clockwise direction and, during the second half or return stroke, will rock in a counter-clockwise direction. Since the pin lever 86 is fast on the shaft 87, it too will be rocked with each machine cycle to shift the link 85 and arm 83 longitudinally to control the movement of the accumulator wheels 78 into and out of engagement with the racks 48. As shown in Fig. 3 the link 85 is connected at its forward end to the upper end of an upstanding link 97, which is, in turn, connected at its lower end, to a lever 98 loosely mounted on a shaft 502. Secured to the shaft 502, and adapted to operate the lever 98 when the shaft is rocked, is an arm 503 (see Fig. 37) bearing a laterally extending stud 504 positioned in front of an upstanding arm of the lever 98. The shaft 502 is journaled between the side frames of the machine and is adapted to be rocked, in a manner later to be described, only during grand total cycles. The point of connection between the link 97 and the link 85 is a pin and slot arrangement and a spring 96 tensioned between the lever 98 and the link 85 serves normally to retain the pin on link 85 in the bottom portion of the slot in link 97. As illustrated, the accumulator wheels 78 normally stand disengaged from the racks 48 with the link 85 and arm 83 in their extreme rearward position, and the link 85 is so positioned with respect to the pin lever 86 as to prevent engagement of either notch 85A or 85B by its respective pin 86A and 86B. The link 85 is held in this position by the following means: As shown in Fig. 37, the upstanding arm of the lever 98 is formed with a stud 505 at its upper end, which stud is adapted to be engaged by the nose of an arm 506 loosely mounted on a shaft 99. The lever 98 is urged in a counter-clockwise direction by means of a

spring 507 but is normally held slightly rocked, in the position shown, by the engagement of arm 506 and stud 505 against the tension of this spring. The link 85 is thus normally held in the intermediate position shown and, during this time, the movement of pin lever 86 will be ineffective with respect to the link and the accumulator wheels 78 will remain in their disengaged or non-add position. In accordance with the 10 previously stated function of the front accumulator, the wheels 78 must remain disengaged during all normal accumulating cycles but must be moved to engaged position during a portion of each total cycle to receive the data being 15 cleared from the rear accumulators. The shaft 99 upon which the arm 506 is loosely mounted is the total shaft of the machine, and it is through the rocking of this shaft that the front accumulator is conditioned to receive the data 20 taken from the rear accumulators. Fast on the shaft 99, adjacent to the arm 506, is an arm 508 connected to the arm 506 by means of a spring 509 and adapted to disable the blocking arm by 25 means of a stud 511. The stud 511 extends laterally across the top of the arm 506 and inasmuch as the direction of motion of the shaft 99 is clockwise as it is rocked from normal (Fig. 37), it will be seen that this movement will rock the arm 506 downward, thereby permitting the 30 previously mentioned spring 507 to rock the lever 98 a short distance in a counter-clockwise direction to elevate link 97 and link 85. The shaft 99 is rocked only during total cycles and at the very beginning of this cycle so that before the pin 35 lever 86 begins to move during the total cycle the link 85 has moved upward with its upper edge limiting against the top pin 86A. Now, during the forward stroke of the total cycle the lever 86 rocks clockwise as viewed in Fig. 37 and 40 does not effect movement of the link 85 so that the wheels 78 remain disengaged. During the first half of the cycle the type carriers 51 and actuating racks 48 are positioned from the rear accumulators and at about the middle of the 45 cycle printing is effected. When the pin lever 86 reaches its fully operated position, the pin 86A thereon overlies its associated notch 85A and the link 85 moves a slight additional distance upward to cause a positive engagement of the notch 50 and the pin. Now, during the return stroke of the machine, the lever 86 moves in a counter-clockwise direction at the very start of the return stroke and shifts the link 85 and arm 83 forward to engage the accumulator wheels 78 and their 55 racks 48. The wheels 78 will then turn proportionate distances according to the distance required for their respective racks to return to normal, as is well known in the art. At the end of the total-cycle, therefore, the wheels 78 are 60 in engagement with their racks and the pin 86A on lever 86 is still engaged by the notch 85A in link 85. Also, at the end of this cycle, the total shaft 99 is restored to normal but the arm 506 loosely mounted thereon is held downward 65 against the tension of spring 509 by the stud 505 which at this time overlies the arm. Thus, at the start of the forward stroke of the first cycle following a total cycle, the link 85 and arm 83 are shifted rearwardly by the pin lever 86 and the wheels 78 are again disengaged from their racks. In order to reset the control mechanism to its normal position, there is provided a restoring arm 512 fast on the accumulator rock 70 shaft 92. The restoring arm 512 extends forwardly in the machine and overlies a stud 513

on the lever 98. During the forward stroke of the first cycle, following a total, therefore, the arm 512 will rock downward and will return the lever 98, link 97, and link 85 to their normal intermediate position, whereupon the arm 506 will again rise to its regular blocking position in front of the stud 505 and the accumulator wheels 78 will remain disengaged until the next total taking operation. It will be observed that the restoring arm 512 will descend during total cycles as well as other cycles and will at this time operate the lever 98 and its associated linkage in the same manner as above. However, the shaft 99 is held rocked throughout the full total cycle so that the blocking arm 506 will be held down through this means and when the pressure of arm 512 is released, the parts will return immediately to their operating position.

In taking a grand total from the front accumulator, the above timing is reversed. That is, during the first half of the grand total cycle, the wheels 78 are engaged with their racks and, in returning to zero, position the type carriers 51 in the usual manner. During the second half of the grand total cycle the wheels are disengaged. This is accomplished by rocking the grand total shaft 502 at the start of the grand total cycle to rock the lever 98 a short distance in a clockwise direction through the previously mentioned arm 503 and thereby engage the bottom notch 86B in the link 85 with the bottom pin 86B on the lever 86. The shaft 502 remains rocked throughout a full grand total cycle so that, during the forward stroke of this cycle, the link 85 and arm 83 are shifted forward and, during the return stroke, are shifted rearward.

Another and well known function of the machine during all total and grand total cycles is the depressing of the zero stops 49 (Fig. 3) to permit free forward movement of the type carriers 51 and actuating racks 48 during these cycles. Referring to Figs. 3 and 36, it will be seen that there is positioned above and between the drive shaft 3 and the previously mentioned rock shaft 57, a third shaft 514 journaled between the side frames 8. As shown in Fig. 3, there is fast on the shaft 514 a forwardly extending finger 515 which overlies the previously described bail rod 55 adapted to depress the zero stops. The shaft 514 may be called the rear total shaft since it is rocked simultaneously with the front total shaft 99, and is only rocked during total cycles. The direction of motion of the shaft 514, as it moves from normal, is counter-clockwise as viewed in Fig. 3, so that during total cycles the finger 515 rocks the bail rod 55 downward to hold all the zero stops 49 depressed in the manner previously described. The means for holding the zero stops 49 depressed during grand total cycles comprise, as shown in Fig. 36, an upstanding arm 518 fast on the grand total shaft 502 outside the left-hand frame piece 3, a rearwardly extending link 517 connected by pin and slot means to the arm 516, and a second arm 518 connected to the rearmost end of the link 517 and secured to the rock shaft 57. It will be recalled that the shaft 57 is normally held rocked in effective position, with the zero stops 49 depressed, by the cam 501 on the left-hand end of the drive shaft 3. In this position of the shaft 57, the link 517 is held rearward and the pin on arm 516 is positioned in the forward end of the slot in link 517. As the high point of the cam 501 moves away from its follower arm 500, the shaft 57 rocks in a clockwise direction (Fig. 36),

thereby releasing the zero stops and moving the link 517 forward, this movement being permitted by reason of the slot at the forward end of the link. During grand total cycles, however, the shaft 502 is rocked before the link 517 begins to move forward and, since the rocking of this shaft will place the pin on arm 516 in the rear end of the slot in link 517, the link, and, therefore, the shaft 57 also will be prevented from moving, so that the zero stops 49 will remain depressed during this cycle.

ACCUMULATOR CONTROL—Rear

As previously mentioned, the rear accumulating mechanism is comprised of one large unit split up into three smaller units or sections. One section accumulates and controls the printing of the "first No.", another controls the printing of the "last No.", while the third accumulates and controls the printing of the total number of cards in each group. As shown in Fig. 3, there is connected to each of the type carriers 51, a rearwardly extending link 519 which is, in turn, connected to an actuating rack 521. Referring also to Fig. 39 it will be seen that the twenty-five actuating racks 521 are supported between a pair of frame plates, or brackets, 522 secured to a pair of fixed cross bars 523 and 524. Six of these racks 521, positioned at approximately the middle of the unit cooperate with the previously mentioned storage sectors referred to on page 1 to control the printing of the "last No." The sets of racks to the right and left of the middle set are adapted to cooperate with accumulating wheels 525 arranged just above the racks 521 on a shaft 525A. The shaft 525A is supported between a pair of arms 526 pivotally mounted on cross rod 526a extending between the frame pieces 522 and is adapted to be raised and lowered thereby to move the wheels 525 out of and into engagement with the racks 521. The shaft 525A extends transversely above all of the racks 521 and in a standard twenty-five column assembly would be provided with an accumulator wheel 525 for each actuating rack 521. In the present machine, however, the six wheels which would ordinarily overlie the "last No." section of the unit have been removed in order that this portion of the unit may operate in a new manner later to be described. Connected to each of the arms 526 is a downwardly extending link 527 connected, at its lower end, to an arm 528 fast on a transverse rock shaft 529 journaled between the side frames of the head. Under control of the shaft 529 the accumulator wheels 525 are caused to move into and out of engagement with their racks, 521, during certain portions of each machine cycle. As shown in Fig. 3, the wheels stand normally engaged with the racks, but at the start of each regular accumulating cycle the shaft 529 is rocked a short distance in a clockwise direction to raise the wheels out of mesh. The wheels remain out of engagement for the entire forward stroke, during which time the racks 521 move forward with the type carriers 51 to the position indicated by the set-up stop bars 47. At the start of the return stroke, the wheels 525 descend into engagement with the racks and receive the entry in the well known manner. When taking a total from the wheels 525, the wheels are permitted to remain in engagement with the racks during the first half cycle and are disengaged therefrom during the second half cycle. During grand total cycles the wheels and racks are disengaged throughout the

entire cycle. The control of the rear accumulator wheels 525 thus resides in the rocking of the shaft 529.

As shown in Fig. 4, the shaft 529 extends outside the right-hand frame wall 8 and there is secured to the extreme righthand end of the shaft a downwardly extending arm 531. Connected to the lower end of the arm 531 is a forwardly extending link 532 formed with a stud 533 at its forward end. Adapted to cooperate with the stud 533 is a pair of bell-crank levers 534 and 535 pivoted to respective frame supported studs 536 and 537. The levers 534 and 535 are operable in a well known manner by a cam (not shown) mounted on the drive shaft 3. This cam is so formed as to impart separate successive motions to the levers 534 and 535. That is, at the beginning of each machine cycle the lever 534 is rocked in a counter-clockwise direction and held rocked, until the end of the forward stroke and then released. At the beginning of the return stroke the lever 535 is rocked in a clockwise direction and at the end of the return stroke, this lever is released. The link 532 is movable up and down in such a manner as to permit the stud 533 thereon to be engaged by one or the other of the levers 534 or 535 but not by both in the same cycle. A spring 538 tensions the link upward into engagement with the lever 535 but the link is normally held downward in the position shown, against the tension of spring 538, in which position the stud 533 on the link may be engaged only by the lever 534. The means for holding the link 532 downward lie in an overlying stud 539 formed on the rear end of a bell-crank lever 541 secured in a manner not herein shown to the previously described rear total shaft 513 (see Fig. 3). In view of the above construction it will be apparent that in the normal operation of the machine the link 532 will be drawn forward by the lever 534 at the start of each machine cycle to disengage the accumulator wheels 525 and that at the start of the second half of each machine cycle the wheels will be permitted to return to engagement and they will be set by the returning racks 521. The lever 535 operates ineffectively during all normal accumulating cycles. During total taking cycles this normal timing is reversed and the wheels 525 are permitted to remain in engagement with their racks during the first half cycle in order that they may be cleared and thereby position the type carriers 51. This function is obtained through the rocking of shaft 514 which, as was previously mentioned, is rocked only during total cycles. This shaft 514 rocks in a counter-clockwise direction and in so doing it is evident that the rear end of bell-crank lever 541, secured thereto, will move upward in a counter-clockwise direction allowing the spring 538 to draw the link 532 upward to permit the engagement of its stud 533 by the lever 535. The shaft 514 is rocked at the very start of the total cycle so that the lever 534 will be rocked ineffectively during this cycle and the accumulator wheels 525 will not be withdrawn from their racks until the start of the second half of the cycle.

It will be recalled that in this machine grand totals are taken from the front accumulator wheels 78. Therefore, during grand total cycles 70 the rear wheels 525 must be moved out of engagement with their racks at the start of this cycle and held out throughout the entire cycle. For this purpose there is provided a latch 542 (Fig. 4) pivoted to the side frame 8 and adapted to engage

5 a downwardly projecting toe of the previously described arm 531. The latch 542 is urged into contact with the arm 531 by means of a spring 543 but is normally held out of engagement, in the position shown, by means of a fingerlike extension of a link 544. This extension lies adjacent the pin 543a on the upper end of latch 542 to which pin one end of spring 543 is connected as shown in Fig. 4. When this extension is moved rearwardly it pushes against pin 543a against pull of spring 543 and holds latch 542 out of engagement. The link 544 serves a second purpose not pertinent to the present invention, and is adapted to be moved a slight distance forward by means of another link 545 connected thereto. The link 545 extends towards the front of the machine and has its front end connected to the upper end of a lever 546 pivoted at its mid point and connected at its lower end to a longitudinal link 547. The link 547 is connected, at its forward end, to an arm 548 fast on the front grand total shaft 502 so that when this shaft is rocked the link moves rearwardly. It is evident that rearward movement of the link 547 will rock the lever 546 in a counter-clockwise direction to draw the links 545 and 544 a short distance forward. Forward movement of the link 544 will enable the spring 543 to rock the latch 542 upward into contact with the arm 531. The shaft 502 is rocked at 10 the start of the grand total cycle and at about the same time the lever 534 is actuated to draw the link 532 and arm 531 forward in the above described manner. Forward movement of the arm 531 will enable it to be engaged by the latch 542 so that the rock shaft 529 will thus be held in 15 operated position and the wheels 525 will consequently remain out of engagement throughout the entire grand total cycle.

It will be recalled that the "first No." section 20 of the rear accumulator unit is adapted to accumulate and control the printing of only the first number of a consecutive order. It will also be recalled that the serial number of each successive card is set up on the stop bars 47 associated with this section and that a means is provided for blocking the movement of the sectors associated with this unit or section during all machine cycles except the one immediately following a total and, of course, the total cycle itself. This means resides in a naught block, mounted on the translator, which is adapted to hold elevated the six zero stops in the "first No." unit during all cycles except those named above. Referring now to Fig. 3, it will be seen that the above naught block is slidably mounted on the rear of the translator 36 below the "first No." unit and is indicated therein by the reference character 132. The upper end of the block 132 is bent over the top of the translator 36 and lies 25 just under the six zero stops of the "first No." unit. The block 132 is spring-tensioned downward and, with the machine in rest position, it occupies the position shown in Fig. 3. If, however, the block is caused to move upward, (by means soon to be described) the result will be a positive elevation of the associated zero stops 48, and the sectors 48 and 51 will be blocked from movement beyond that point. As shown in Figs. 3 and 5, the block 132 is connected, through an arm 135, to a shaft 136 supported at the rear of the translator. The shaft 136 is rotatably mounted between a pair of brackets 137 (one shown) fastened to the rear of the translator. The arm 135 is fast on the shaft 136 and it is 30 evident that, if the shaft is rocked in a clock-

wise direction, as viewed in Fig. 3, the block 132 will be elevated to perform the function stated above. The shaft 136 is adapted to be rocked through the medium of a cam 138 secured to the constantly rotating shaft 3. As shown in Fig. 3, the cam 138 is formed with a single low spot or depression 139 and is adapted to cooperate with a roller bearing arm 141 pivoted at 142 to the rear of a bracket 143 fastened to the previously mentioned stop tray 46. The arm 141 extends forwardly at its pivot 142 and overlies a stud 144 formed on the upper end of an arm 145 fast on the shaft 136. The arm 141 is urged to move in a counter-clockwise direction (Fig. 3) about its pivot 142, to maintain its roller in contact with the periphery of the cam 138, by means of a spring 146 tensioned between the arm 141 and a fixed stud on the stop tray 46. Thus, it will be seen that, unless otherwise influenced, the arm 141 will move in a reciprocating rocking motion, due to the formation of cam 138, once for each cycle of the shaft 3. This motion is transmitted through the arm 145 to the shaft 136 to elevate the block 132 in the manner described above. As shown in Figs. 4 and 9, however, mechanism is provided whereby the shaft 136 may be latched in rocked position upon its first actuation following a total stroke in order that the block 132 will remain elevated so long as the record cards follow one another in sequential order. Secured to the extreme right-hand end of the shaft 136, and positioned just outside the right-hand bracket 137, is a downwardly extending finger 148. Pivoted at 149 on the bracket 137 is a second arm or finger 151 positioned below but in the same plane as the finger 148. The arm 151 is urged, by means of a spring 152, to move in a clockwise direction (Fig. 9) and a forwardly extending portion of the arm is adapted to engage the finger 148. It is evident that, if the shaft 136 is rocked in a clockwise direction (Fig. 4) the arm 151 will be permitted to move clockwise under tension of its spring to place the forwardly extending portion of the arm beneath the finger 148. The shaft 136 is thus held rocked in operated position to keep the block 132 raised. A forwardly extending link 153 (Fig. 9) is connected to the arm 151 and operates under certain conditions of operation, later to be described, to disable the arm.

TOTAL CONTROL MECHANISM

In view of the preceding description of the accumulator control mechanism, it will be seen that the immediate means for controlling this mechanism during total taking cycles lies in the operation of the several total shafts 99, 502 and 514. The shafts 99 and 514 are rocked during the regular group total cycles, while the shaft 502 is rocked during grand total cycles. These shafts are adapted to be rocked through means that are old and well known in this type of machine and only a brief description of these means will be given herein. A patent showing this general type of means for operating the total shaft is U. S. Patent No. 2,066,406, issued January 5, 1937, to W. W. Lasker. As shown in Fig. 36, the total shaft 99 is connected, by means of an arm 549 fixed thereon and a link 551 connected to the arm, to a lever 552 fixed on a stub shaft 552a journaled on an auxiliary frame member 122. Formed on the lever 552 is a stud 553 adapted to be engaged by one side of a T-shaped head formed on a link 118 (see Fig. 5A). The

link 118 is urged into contact with the stud 553 by a spring 554 and is adapted to be pulled downward during total cycles to rock the lever 552, and thereby the shaft 99. Movement of the lever 552 is also caused to rock the rear total shaft 514 through an arm 555, fixed to the stub shaft 552a operable by the lever 552, a link 556 connected at its forward end to the arm 555 and at its rearward end to an arm 557 fast on the shaft 514. The link 118 is the well known T-link of the machine and is operable from the automatic total control unit (later to be described). The link 118 normally stands in the position shown, but, during grand total cycle, it is shifted a short distance rearwardly and is then pulled downward in its new position to rock the grand total shaft 502. In its grand total pulling position, the link 118 is adapted to operate directly upon a lever 119, and this lever is connected through collar 121A, arm 123, link 124, and arm 125, to the shaft 502. Referring to Fig. 5A it will be seen that a stub shaft 121 is anchored in auxiliary plate 122 and on it is disposed a rotatable collar 121A. Arm 119 is fastened to one end of this collar and arm 123 to the other and both move therewith. Link 118 is adapted to engage stud 553a on arm 119 and arm 123 is connected to link 124. In order that the link 118 may be shifted rearwardly, during grand total cycles, there is connected thereto a rearwardly extending link 558 (Fig. 36) connected at its far end to an arm 559 fast on a shaft 561 supported by the auxiliary frame 122. Also fast on the shaft 561 is a forwardly extending arm 562 to which is connected a downwardly extending link 563. The link 563 is adapted to be pulled downwardly by a cam on the automatic total control unit, in a manner later to be described, thereby rocking the shaft 561 counter-clockwise (as viewed in Fig. 36) to shift the link 118 rearwardly.

In all of the Powers tabulating machines, there is provided an automatic control unit which initiates both total and grand total operations or total operations alone from a change in designating number or through any other suitable means made necessary by the particular function performed by each machine. A total control unit similar to the one employed herein is described in the U. S. patent to John T. Ferry, No. 2,185,841, issued January 2, 1940, and also in the U. S. patent to W. W. Lasker, 2,237,908, issued April 8, 1941. Figs. 3 and 4 of Patent No. 2,185,841 and Figs. 7 and 8 hereof are comparable views illustrating the same subject matter.

As explained in the timing diagram to follow, the present machine initiates the taking of a total at a point slightly later in the machine cycle than is customary in the standard Powers tabulator. To compensate for this change in timing certain minor alterations in some of the cams of the total unit and the card feed cam have been made. In all of its essential features of construction and operation, however, the total control mechanism of the present machine is the same as that described in the above mentioned applications, a detailed description of which is given therein. The total control mechanism of the above applications and the present machine is comprised in a normally inactive cam and ratchet unit adapted to be controlled by a pair of cams 101 and 102 (Fig. 7) secured to the shaft 2. Each cam 101 and 102 operates an associated push rod numbered, respectively, 103 and 104. Resting on top of the push rod 103 is

a pawl arm 105 adapted to cooperate with a ratchet wheel 106 fixed on a shaft 107. The pawl arm 105 rises and falls with the push rod 103 but because of the arrangement of teeth on the ratchet wheel 106, the pawl is normally unable to advance the ratchet wheel and, therefore, cannot rotate the shaft 107. The push rod 104 cooperates with a pawl arm 108 adapted to advance a ratchet wheel 109 also secured to the shaft 107. The pawl arm 108 is, however, normally latched upward, out of the scope of movement of the push rod 104, by a latch 111 pivoted to a short shaft 112. As long as the latch 111 remains effective, therefore, the cam 102 is unable to operate the arm 108 and the shaft 107 remains stationary. Cooperable with the latch 111 is an arm 113 secured to a shaft 114. As viewed in Fig. 7, the rocking of shaft 114 rearwardly will disable latch 111, permitting the arm 108 to drop downward until it limits against the top of the push rod 104. Now, upon the next elevation of the rod 104 by the cam 102 the pawl arm 108 will advance the ratchet wheel 109 and the shaft 107 one step. The one step of movement thus imparted to the shaft 107 so positions the first mentioned ratchet wheel 106 as to permit its advancement by its pawl arm 105 during each of the next two succeeding cycles of the cam 101. During the above mentioned three steps of movement of the shaft 107, a complete total-taking operation takes place and at the end of this period the total control mechanism is completely normalized with the parts in their original rest position. As fully explained in the above mentioned Patent No. 2,185,841, the first step of the shaft 107 serves to disable the card feeding and sensing mechanisms and to keep the card stop 18 lowered to retain the card which initiated the taking of the total in the sensing chamber. The second step of operation of the shaft 107 serves to retain the above disabling mechanism in operative position and also to place the rise on a cam 115 (Fig. 8) beneath a roller on an arm 116 pivoted at 117 and connected to the link 118. The second step of shaft 107, therefore, pulls downward the link 118 to rock the total shafts 99 and 514 in the previously described manner. The third step of movement of the shaft 107 normalizes the total control mechanism and conditions the machine for a positive sensing of the first card of a new group. The mechanism very briefly described above relates only to the means for releasing a total from the rear accumulators.

A grand total taking operation is performed by causing the total unit to go through two successive series of operations, that is, it moves in six successive steps and the machine is put through two total taking operations. The total cycle and the grand total cycle is separated by the usual space or blank stroke, and, during this blank stroke, the T-link 118 is shifted from its total position to its grand total position. The grand total mechanism of the control unit comprises a detent cam 564 (Fig. 7), a ratchet wheel 565, and a shift cam 566, all three of which are fastened together and loosely mounted on the shaft 107. The ratchet wheel 565 is adapted to be rotated by a feed pawl 567 operable by a branch of the push rod 104 previously mentioned. The pawl 567 is, however, normally held in ineffective position by a latch 568, which latch may be disabled by an arm 569 fast on a control shaft 571. As described in the above application, the control shaft 571 is rocked only to institute

grand total operations and is then rocked in unison with the other control shaft 114. Thus, the control unit may cause total-taking operations to be performed alone, but grand total-taking operations must always be preceded by a total operation. The detent cam 564 operates to prevent the normalizing of the control unit after the first three steps of a grand total operation and the shifting cam 566 shifts the T-link 118 to grand total position through a follower arm 572, the link 563 and the above described linkage.

Returning now to the means for initiating a regular group total-taking operation, it will be seen that anything which rocks the shaft 114 (Fig. 7) counter-clockwise will disable the latch 111 to institute a total-taking operation. As shown in Figs. 8 and 9 a two-arm lever 126 is secured to the right-hand end of the shaft 114 and an upwardly extending link 127 is connected to one arm of the lever. The link 127 is adapted to be pulled upwards in a manner later to be described when a break in the sequential order of the record cards occurs and it is evident that such a motion will rock the shaft 114 counter-clockwise to initiate the taking of a total, as previously described. A standard change of designation mechanism is also provided in the present machine whereby the taking of totals may be initiated through the upper pin box 30 slides 34 when it is desired to use the machine for another purpose than the verification of sequential orders. To this end an arm 128 is also fixed on the shaft 114 and a bail rod 129 is supported between the arm 128 and the lever 126. As shown in Figs. 5 and 8, the bail rod 129 lies directly in front, but beyond the scope of movement of all of the slides 34. Interponents 131 are adapted to be manually and selectively positioned between an associated slide 34 and the bail rod 129. In any column in which the interponent 131 is thus positioned, it is evident that lateral movement of the slide 34 will cause the bail 129 to rock in a counterclockwise direction (Fig. 5), thereby imparting a similar rocking motion to the total trip shaft 114.

It is in this manner that the grand total control shaft 571 is rocked. As shown in Fig. 8, a pair of arms 573 is fast to the shaft 571 and supported between the arms is a bail rod 574 positioned directly beneath the bail rod 129. The interponents 131 are depressable to two positions, in one of which the bail rod 129 may be rocked alone without movement of the bail 574. In the other position of the interponents the bail rod 574 will be rocked and it is evident that, due to the formation of arms 573, this motion will be accompanied by a simultaneous rocking of bail rod 129. As shown in Fig. 8, the last interponent 131 to the right in the figure is positioned in its second position so that any movement of it by a slide 34 will cause both bail rods 129 and 574 to be moved and thereby initiate the taking of a grand total. The movement of the slide 34 in any desired column for this purpose is achieved by means of a special card, having a special perforation, and this card is placed at the end of a series of cards being run through the machine. The use of such a card to operate the grand total mechanism through the change of designation mechanism is well known in machines of this type.

"Last No." retaining device

As mentioned earlier in the description, there is associated with the "last No." portion of the

single accumulating and printing unit certain novel retaining mechanism adapted to control the printing of the last number of each consecutively numbered group. This mechanism is a form of accumulating mechanism wherein each successive serial number is entered during the second half of one cycle and then cancelled therefrom, during the first half of the next following cycle. A break in the consecutive order of the serial numbers will cause a total-taking operation and, under the control of the automatic total control unit, the action of the retaining mechanism is so modified at this time as to prevent the cancellation therefrom of the last number of the consecutive order. During the total cycle, this number is withdrawn from the retaining mechanism, is printed, and is then rolled into the grand total accumulator in front of the machine. Referring to Figs. 37 and 39 it will be seen that the six racks 521 in the "last No." section of the rear accumulator unit are of slightly greater length than the remainder of the racks in the unit and that the engaging teeth thereon are set farther back than the teeth on the other racks. Each of these special racks is adapted to be engaged by a gear sector 575. The six gear sectors 575 are loosely mounted on a shaft 576A supported between the rear ends of a pair of arms 576 pivoted, at 526a, to the respective side plates 522. The sectors are urged in a clockwise direction (as viewed in Fig. 37) by springs 577 connected thereto and anchored to a fixed bracket 578 supported between upstanding arms of the frame pieces 522. Movement of the sectors in a clockwise direction is limited by set screws 579 projecting through a cross bar 581 supported between the arms 576 and overlying the forward edge of the sectors. Due to the tension of the springs 577, therefore, the sectors 575 normally occupy the position shown which is their zero position. The assembly comprising arms 576, cross bar 581, and the sectors 575 is adapted to be raised and lowered once for each machine cycle to disengage and engage the sectors with the six actuating racks 521. Connected to each arm 576 is a downwardly extending link 582 connected at its lower end to an arm 583 fast on a shaft 584. The shaft 584 extends only part way through the machine and is supported for free rotating movement at its left-hand end by a bracket 585, fixed to the left-hand side frame 8, and at its right-hand end by downward extensions of the brackets 522. Also fast on the shaft 584 is a forwardly extending arm 586 bearing a roller 587 adapted to ride the periphery of a cam 588 secured to the drive shaft 3. The shaft 584 is urged in a counterclockwise direction (Fig. 37) to maintain the roller 587 in contact with the cam 588 by means of an upstanding arm 589 fast on shaft 584, to which is connected a spring 591 extending from the previously mentioned spring anchor 62. The outer edge of the cam 588, it will be seen, is formed with a single depression 592, which is equivalent to approximately one-third of the total circumference of the cam. All of the above parts are normally positioned as shown, with the roller 587 on arm 586 resting on the high outside surface of the cam 588 and the gear sectors 575 engaged with their racks 521. It will be recalled that in this "last No." unit each successive serial number is set up on the stop bars 47 associated with this unit, and the type sectors 49 and 51 are positioned in accordance with this setting. Since the

actuating racks 521 are connected to their associated type carriers 51, these racks will, of course, move in unison with the carriers and also be positioned to the representation of the serial number. The actuating racks 521 move forward during the first half cycle and are restored to normal during the second half cycle so that to enter the serial number into the retaining sectors 575, the sectors must be moved to disengaged position during the forward movement of the racks, and to engaged position during the return movement of the racks. The direction of motion of the drive shaft 3 is clockwise, as viewed in Fig. 37, and it will be seen that at about fifty-five degrees after the start of each machine cycle the roller 587 will begin to drop into the depression 592 in cam 588 as the shaft 584 moves in a counter-clockwise direction under the tension of spring 591. This motion of the shaft 584 is imparted, through the arm 583 and link 582, to the sector supporting arms 576 and the sectors 575 are moved upward, thereby to their disengaged position. As explained in the timing diagram to follow, the actuating racks 521 do not begin to move forward until approximately seventy degrees after the start of the cycle so that by this time the sectors 575 are entirely disengaged therefrom. The racks 521 then move forward and are positioned in accordance with the setting of the stop bars 47 and midway in the cycle begin to return to normal. However, the racks have a short period of dwell in their extreme forward position and during this period the roller 587 on arm 586 rides out of the depression 592 in cam 588, thereby rocking the shaft 584 back to normal and lowering the sectors 575 into engagement with the racks. Now, as the racks 521 return to normal, the sectors 575 are moved away from their zero position against the tension of springs 577, each sector being turned a number of tooth spaces equivalent to the distance required for its associated rack to reach its normal position. The sectors 575 are thus positioned to the representation of the serial number set up during this cycle and will retain this setting until they are moved to disengaged position during the next following cycle. It is evident that as soon as the sectors are disengaged from the racks, they will return immediately to their zero position under tension of the springs 577.

This retaining mechanism will operate in the above manner throughout all normal accumulating cycles, or as long as the serial numbers follow one another in consecutive order. It will be apparent, however, that, when a break in the consecutive order occurs and the resultant totaling operation takes place, the action of the retaining mechanism must be modified in such a manner as to permit the racks 521 and the six type carriers 51 connected thereto to be positioned by the sectors 575 in order to effect printing of the last number of the consecutive order. This is done by rendering the cam 588 ineffective during total cycles so that the sectors 575 remain in engagement with the racks 521 throughout the total cycle and, when the racks move forward at the start of this cycle, they are positioned in accordance with the distance required for the sectors to reach their zero position. As shown in Fig. 37, there is fast on the shaft 584 a forwardly extending arm 593 connected to the upper end of a downwardly extending link 594. The link 594 extends down through the intermediate portion of the machine and is connected at its lower end

to an arm 595 fast on a stub shaft 596 supported by a bracket 597 fixed to a casting 598. The casting 599 constitutes the supporting means for the previously described total control unit and is mounted on the left-hand side of the machine just above the base. Also fast on the stub shaft 596 is another arm 599 bearing a follower roller 601 cooperative with a cam 602 of the total control unit. The cam 602 is fast on the shaft 107 and, as explained in Patent No. 2,185,841, is the cam, regularly employed to disable the card feeding mechanism during total-taking operations. In the present machine, this cam serves the dual purpose of disabling card feeding and rendering the sector cam 588 ineffective. The cam 602 moves with the shaft 107 in three step-like motions during total-taking operations and during the first two of these steps one of the three high points of the cam is positioned directly in front of the roller 601 on arm 599, thereby preventing movement of this arm and its associated linkage at this time. In the normal position of the cam one of the three low spots thereon is opposite the roller 601 so that normally the arm 599 is permitted free movement forward and rearward under control of the shaft 584. Upon the first step of movement of the cam 602, however, a high spot thereon moves into the path of the roller 601, thereby locking the shaft 584 against operation and preventing the disengagement of the sectors 575 from their racks 521 at this time. The cam 602 remains in effective position for a length of time equivalent to two machine cycles, one of which is the blank cycle preceding a total and the other the total cycle itself. The cam 588 is thus rendered ineffective for two machine cycles, and the "last No." is not cancelled therefrom until the first part of the cycle following the total stroke.

As before mentioned, each "last No." is entered into the grand total accumulator wheels 78 in a previously described manner. Now, when it is desired to clear the wheels 78 and obtain a grand total, it is evident that the gear sectors 575 must be disengaged from their racks during the forward stroke of this grand total cycle. Inasmuch as the cam 602 is in effective position during the grand total cycle, it will be seen that some intermediate means must be provided, between the cam and the shaft 584, to permit the shaft to rock in its usual manner during the first part of this cycle. To this end the point of connection between the previously mentioned arm 593 and the link 594 is made a pin and slot means with the slot, which is formed in the link, being of such angle-shaped form as to normally permit no lost motion between the two elements. Rearward movement of the link 594, however, will place the longitudinal portion of its slot in cooperative relation with the pin on arm 593 so that the arm and the shaft 584 may be rocked independently of the link. In order to move the link 594 rearwardly, during grand total cycles, there is connected thereto a forwardly extending link 603 (Fig. 37) connected at its front end to an arm 604 fast on the grand total shaft 502. The rocking of shaft 502, in the previously described manner, will shift the link 594 rearward to serve the above purpose.

As explained earlier in the description, grand total mechanism is provided in the present machine in order to make possible a simple means of checking the tabulation of the cards.

Fig. 38 illustrates a completed listing and the manner of proving the correctness of the listing.

As shown therein the separate grand totals of the "first No.," "last No.," and "total" are printed just below their respective columns. Now, in order to prove the listing it is necessary for the checker to subtract the grand total of the "first No." from the grand total of the "last No." and then subtract this difference from the grand total of the "total." In the problem illustrated, this final difference is "three," and this number is then checked against the number of total-taking operations performed during the tabulation. Since there were three total-taking operations in the problem illustrated, exclusive of the grand total, this listing is correct. This final difference and the number of total taking operations will always be the same if the numbers have been correctly listed. In view of the fact that a set of cards is usually divided into a great many consecutively numbered groups, a counter is provided on the machine for counting the number of total taking operations performed during a run of cards. This counter and its connection to the machine is shown in Fig. 37 and is indicated therein by the reference character 605. The counter 605 is connected to the front total shaft 99 by means of a link 606 and an arm 607, fast on the shaft, so that each time the total shaft is rocked, the counter is actuated.

TRANSLATOR PIN BOX

The remaining portion of the specification is devoted to a description of the mechanism for comparing the serial number of each successive record card with that of its predecessor, and for initiating the taking of a total when the sequential order of the record cards is broken. This mechanism is exactly the same as that disclosed in my Patent No. 2,280,924. Referring to Figs. 6 and 10, it will be seen that the previously mentioned pin box secured to the front of the translator 36 at its right-hand side is comprised of a pair of plates 158 and 159, held in rigid alignment and a third plate 162 spaced a short distance in front of the plate 159 and fastened thereto by screws 163, the unit being secured to the translator 36 by screws 161 (Fig. 6). The wires 37C operated by the wires 37 extend through an opening in the frame of the translator and are secured at their forward ends in the plate 158. Since the machine of the invention is built to operate on cards having serial numbers of six digits or less, there are six columns of wires 37C. Each column of wires represents in order from top to bottom, the numerals nine, seven, five, three, and one. There are, however, as is shown in Fig. 10, six wires to each column. The lowermost wire in each column, indicated herein at 164, is a zero wire operated from a zero hole punched in the card. There are only six zero wires 164 in the entire translator (one for each column in the pin box) and these six wires are associated with the zero positions in the field of the card which contains the serial number. For a purpose later to be explained a "zero" is punched in each column of this field wherein a digit of the serial number does not appear. For example, if the serial number of a card is 785 then the three extra columns to the left of the 7 would be punched with zeros, this field being comprised of six columns as previously mentioned. A zero is also punched if it appears in the serial number itself.

As shown in Fig. 10 there is positioned in front of each column of wires 37C and 164 a column 75 of pins 165 supported between the plates 159

and 162. The operation of any wire 37C or 164, therefore, will cause a forward movement (to the left as viewed in Fig. 10) of its associated pin 165. The special wire 42 which also extends into the above pin box operates a similar pin 165a, supported between the lower left-hand corners of the plates 159 and 162 (Fig. 6) in a manner similar to the above.

COMPARING UNIT

(Decoding pin box)

The comparing mechanism of the machine is controlled through the medium of the pins 165 and is contained in a unitary structure mounted directly in front of the plate 162 of the pin box and secured to the base casting 5. The comparing unit is formed of a pair of frame plates 166 and 167 (see Figs. 9, 11, 12, and 13) between which are mounted the various counting and sensing mechanisms. As shown in Fig. 11 the frame piece 166 is bent inward at its lower end and is rigidly mounted on the base casting 5. The plate 166 is further held in a rigid position by means of a bolt (not shown) connecting a forward extension of the plate to the translator frame. The plate 167 is held in rigid alignment with the plate 166 by means of tie rods 168 and various shafts to be noted with more particularity in their proper place in the description. Cut in the front edge of each plate 166 and 167 is a horizontally extending slot 169 (Figs. 12 and 13). Supported between the slots 168 is a pin box 169 (Figs. 14 and 31) formed with lateral oppositely extending studs 171 adapted to extend through the respective slots 168. The forward and rear ends of the box 169 are enclosed by plates 172 (see also Fig. 15) between which are supported six columns of pins 173, there being ten pins to each column. The pin box 169 is thus loosely mounted between the side frames 166 and 167 and mechanism is provided whereby it may be reciprocated forwardly and rearwardly once for each cycle of the machine. As shown in Figs. 12 and 13 the respective studs 171 extend beyond their frames 166 and 167 and each is cradled in the upper end of an arm 174 secured to opposite ends of a shaft 175 loosely mounted between the side frames. Referring now to Figs. 1, 9, 12, and 16, it will be seen that fast on the right-hand end of the shaft 175 is a forwardly extending arm 176 connected at its far end to a downwardly extending link 177. The link 177 is connected at its lower end (Figs. 1 and 16) to one end of a lever 178 pivoted at its mid point to a shaft 179 (see Fig. 17) supported at one end by the inner framework of the machine and at its other end by a bracket 181 (Fig. 1) fixed to the base plate 4. At its other end the lever 178 bears a roller adapted to ride the periphery of a cam 182 secured to the main drive shaft 2. As shown in Fig. 16 the cam 182 is formed with a single rise 183 so that the lever 178 will be rocked in a clockwise direction about its pivot 179 once for each cycle of the shaft 2. This clockwise motion of the lever 178 is imparted through the link 177 and arm 176 to the shaft 175 to rock the arms 174, and thereby by the pin box 169, rearwardly. A pair of springs 184 (Figs. 12 and 13), tensioned between the oppositely extending studs 171 and studs on the respective frame plates 166 and 167, serve to urge the pin box 169 to retain a retracted position and to maintain the roller on lever 178 in contact with its cam 182. The pin box 169 is positioned

directly in front of the previously mentioned pins 165 on the translator and once for each cycle of the machine the pin box 169 is briefly moved rearwardly under the control of cam 182 to enable its pins 173 to contact the pins 165.

Referring again to Fig. 10 it will be seen that each pin 165, except the "nine" and "zero" pins, has a button 185 formed on its forward end. As mentioned above, there are ten pins 173 to each 10 of the six columns, the ten pins representing in order from top to bottom the numerals "nine" to "zero". The reciprocation of the pin box 169 occurs shortly after the translator wires 37 are raised so that as each successive number is set 15 up on the pins 165 the pin box 169 moves rearwardly to permit the extended pins 165 to operate their associated pins 173. The buttons 185 integral with the seven, five, three, and one pins 165 are of a sufficiently large diameter to press 20 upon two pins 173 of one column at the same time. For example, if a five pin 165 is extended, then both the five and six pins 173 of the associated column will be pressed forwardly. An even number is represented on the pins by the 25 odd number of next lower numerical value extended in cooperation with the nine pin. A "six," for example, is obtained by extending the five and nine pins 165 of the same column. In order that the pins 173 may perform a function soon 30 to be described they are locked in operated position for approximately the duration of one machine cycle.

As viewed in Figs. 14, 18, 19, and 20, each 35 column of pins 173 has three locking slides associated therewith. One of the locking slides 186 (Figs. 14 and 18) is positioned to the right of each column of pins and cooperates with extrusions 187 extending to the right of each odd numbered pin 173 and the zero pin. As shown 40 in Fig. 18 the extrusions 187 extend through locking slots 188 cut in the slide 186, said slots being formed with shoulders 189. Each slide 186 is tensioned downward by means of a spring 191 so that it is evident that each time an odd numbered pin 173 is pressed forwardly a locking slide 45 186 will tend to engage the operated pin and hold it extended. As shown in Figs. 18, 19, and 20, all of the number nine pins 173 are shorter in length than their associated pins in the same 50 column. The nine pins are supported at their forward ends by a bracket 180 and operate in a manner soon to be described. Associated with each column of pins 173 on their left-hand side is another locking slide 192 (Figs. 14 and 19) co-operating with extrusions 193 formed on the left-hand side of all of the even numbered pins 173 and the nine pin. As shown in Fig. 19, the 55 extrusions 193 extend through locking slots cut in each slide 192 in much the same manner as the above extrusions 187 on the odd numbered pins 173. However, the extrusions 193 normally lie in the left-hand side of their associated slots (Fig. 19) whereas the shoulders formed therein are on the right-hand side of the slot. Therefore, 60 unless the slides 192 are released to move to the left, in a manner soon to be described, the even numbered pins 173 will not be locked when operated. The third slide associated with each column of pins 173 is also positioned to the left 65 of the column and is numbered 194 (see Figs. 14 and 20). As shown in Fig. 20 each slide 194 is formed with cam slots 195 through which extend the extrusions 193 on the even numbered pins 173. The right-hand end of each slide 194 (Fig. 20) extends out of the pin box 169 and is

formed with a forwardly extending portion 196 lying parallel to the pins 173. Connected by pin and slot connection to the forward end of the extension 196 is a plate 197 tensioned rearwardly by means of a spring 198 connecting plate 197 and extension 196. The slides 194 are urged downwardly by means of springs 199. As shown in Fig. 20 the upper right-hand corner of the pin box 169 is broken away and through this opening extend the several plates 197, the lower rear edge of each being positioned just in front of its associated nine pin 173, and the forward end thereof lying parallel to the forward ends of the remainder of the pins 173 of the unit. The number nine pins are thus adapted to operate their associated plates 197 to project them forwardly to serve the same purpose as the operation of the regular pins 173. From the formation of the cam slots 195 cut in the slides 194, however, it will be seen that the operation of any even numbered pin 173 will cause its associated slide 194 to move to the right (as viewed in Fig. 20) to place the plate 197 connected thereto out of the path of the nine pin.

In the construction of the pin box as thus far described it will be seen that each time a number is set up on the pins 173 the pins of each column will be extended in various combinations. That is, if an odd number is being set up, both the desired odd number pin and the next higher even pin will be extended. If an even number is set up, the desired even number pin, the next lower odd number pin and the nine pin of the same column will all be extended. It is necessary, however, that only one pin 173 per column be locked in operated position. To accomplish this end the slides 186, 192, and 194 are constructed in the following manner. As shown in Fig. 14 each of the number nine pins 173 have two extrusions, 187 and 193, respectively, extending from opposite sides of the pin. The extrusion 187 of each pin extends through a cam slot 201 formed in the slide 186 and which is adapted, when the nine pin is operated, to cam the slide 186 to the left, as viewed in Fig. 18. Therefore, if the nine pin and an odd numbered pin of the same column are operated together, the locking shoulders 189 in the slots 188 will be prevented from performing their normal function of locking the extended odd numbered pins. The extrusion 193 of each of the nine pins extends through both of the slides 192 and 194. The slide 192 is formed with a cooperating slot 202 (see Fig. 19) formed in the shape of an inverted L. The extrusion 193 normally lies in the narrow rear portion of the slot 202 and serves to retain the slide 192 in the position shown in Fig. 19 with the locking slots formed therein out of cooperative relation with the extrusions 193. Thus, an operation of an even numbered pin 173 without a simultaneous operation of the nine pin of the same column will merely be an ineffective movement and the pin will not be locked. If, however, the nine pin is extended in conjunction with an even numbered pin, the extrusion 193 on the nine pin will enter the enlarged portion of the slot 202, thereby permitting the slide 192 to move to the left (Fig. 19) under tension of its spring 191 to lock the operated even numbered pin in extended position. Also cooperating with the extrusion 193 on each of the number nine pins is a slot 203 formed in the slides 194 (see Fig. 20). The slots 203 are open, without either cam surfaces or locking shoulders and serve no function save to provide an opening for the extrusions 193. Any number

nine pin 173 may thus be operated alone to project forwardly its associated plate 197. The zero pins 173 cooperate with the slides 186 and are locked thereby each time they are operated. Individual spring tensioning means, comprising a coil spring 204 (Figs. 18, 19, and 20) surrounding each of the pins 173, is provided to urge the pins rearwardly. If a pin is not locked in extended position, therefore, it will be returned to normal as the pin box 169 leaves the translator pins 165. Mechanism is provided whereby the slides 186, 192, and 194 may be retracted once for each machine cycle to release the extended pins 173 just prior to the time a new number is set up thereon. As shown in Figs. 9, 13, 15, and 21, a bail rod 205 is positioned just beneath the lower rear edges of all of the slides 186, 192 and 194, and is supported between the upper ends of a pair of arms 206 (one shown) secured to opposite ends of a collar 207 loosely mounted on a shaft 208 pivotally supported between the side frames 166 and 167. Fast on the right-hand end of the collar 207 is an arm 209 (Figs. 9 and 13) connected to a downwardly extending link 211. As viewed in Figs. 1, 17, and 21 the link 211 is connected at its lower end to one end of a lever 212 secured at its other end to a collar 213 (Fig. 17) mounted on a stud (not shown) integral with an auxiliary frame piece 210 (see Fig. 1). Fast on the outer end of the collar 213 is an arm 214 bearing a roller at its far end adapted to follow the contour of a cam 215 secured to the shaft 2. The roller on the arm 214 is forced to remain in contact with its cam 215 by reason of the action of springs 191 and 199 working on the slides in the pin box so that it is evident that once for each cycle of the shaft 2 the lever 214 will be rocked in a counter-clockwise direction (Fig. 21) to pull downward the link 211 to rock the arms 206 and elevate the slides 186, 192, and 194 through the bail rod 205. The pins 173 are thus free to return to normal and receive a new set-up from the pins 165.

For each cycle of the machine, therefore, the decoding pin box 169 is reciprocated horizontally a short distance. As will be explained in greater detail in the timing diagram to follow, the pins 173 of the pin box receive their set-up from the translator pins 165 at the start of each machine cycle and then the pin box moves forwardly to enable the extended pins to position certain racks (later to be described). Near the end of each machine cycle the locking slides retaining the pins 173 are retracted and the pin box again moves rearwardly to receive a new number set-up.

RACK SET-UP AND RETAINING MEANS THEREFOR

As shown in Figs. 11 and 15, there is rigidly mounted between the side frames 166 and 167 two shafts 216 and 217. Loosely mounted for vertical reciprocation on the shafts 216 and 217 are six racks 218 formed with slots 219 and 221 through which extend the respective shafts 216 and 217. The racks 218 are urged downward in the position shown in Fig. 15 by means of springs 222 one of which is tensioned between an arm 220 secured to the upper end of each rack 218 and a tie rod 223 mounted between the side frames 166 and 167.

Upon the institution of a total-taking operation, all of the racks 218 are raised to their highest elevated position, through means later to be described, and on the first machine cycle following a total the first number of a new sequential order is set up on the pins 173. Then after the

pin box 169 has moved to its forward position, the racks 218 are permitted to descend. The racks 218 are positioned forwardly of and between the several columns of pins 173 and each rack is provided with a stop plate 224 adapted to cooperate with the pins 173 of its associated column. The plates 224 are mounted on the right-hand side of the racks 218 by means of pin and slot connections and are tensioned towards the rear of the machine by means of springs 225. The length of the plates 224 is exactly the same as the width of the racks 218 and the rear end of each plate lies in front of its associated column of pins 173. Now, during the descent of the racks 218 certain of the plates 224 will limit against extended pins 173, thereby halting the downward movement of its associated rack 218. Cut in the upper rear edge of each rack 218 are ten detent teeth 226 adapted to be engaged by an associated detent pawl 227 pivoted on a shaft 228 supported between the side frames 166 and 167. Springs 229, one of which is tensioned between each of the detent pawls 227 and a tie rod 231 supported between frames 166 and 167, serve to urge the pawls 227 in a counter-clockwise direction (Fig. 15) into engagement with their racks 218. Through means later to be described, however, the detent pawls 227 are held disabled during the period of extreme elevation of the racks 218 and are permitted to engage their racks again only after the plates 224 have limited against the extended pins 173 to set up the new number. As shown in Fig. 15, the distance between the bases of the detent teeth 226 is approximately equivalent to the diameter of one pin 173. When the detent pawls reengage those racks 218 which are limiting against extended pins 173, the nose of each pawl comes to rest between the rack teeth 226 at a point just above one of the teeth with a distance equal to the diameter of a pin 173 separating the pawl nose and the next higher tooth 226. Now, upon the retraction of the locking slides in the pin box, the pins 173 return to normal, thereby permitting the racks 218 which they have held elevated to drop downward the distance required for the lower face of the next higher tooth to limit against the detent pawls 227. At this time, it is evident that the rearmost end of each plate 224 is directly opposite the originally extended pin 173 against which it previously limited.

All of the racks 218 are thus set in accordance with the first number of a new sequential order. Before the pins 173 are set up with the number of the next card, mechanism is provided for increasing by one the numerical representation of the racks 218 by feeding the rack 218 of lowest order one tooth space upwards. If, after the above operation the new number as represented by the extended pins 173, is higher by one than the previous number then all of the plates 224 will be in exact alignment with the operated pins 173 and will be projected forwardly thereby against the tension of their springs 225. During the time the plates 224 are projected forwardly, a sensing or comparing operation takes place in order to determine the relative arrangement of the plates 224 and the pins 173. If, as described above, the plates 224 and pins 173 are in exact alignment, no further operation takes place. The pins 173 will be retracted, the numerical representation of the racks 218 will again be increased by one and the third record card will be sensed. If, however, the plates 224 and pins 173 are not identically arranged, the sensing mechanism will cause a total taking to be initiated; thereby clear-

ing the comparing unit and the rear accumulator and resetting them for a new sequential order.

RACK FEEDING

- 5 The rack feeding mechanism is controlled from a cam on the main shaft and operates once for each cycle of the machine. As shown in Fig. 15 the lower rear edge of each rack 218 has ten teeth 232 cut therein similar to the teeth 226. 10 Fixed to the left-hand side of each rack 218 is a plate 233 positioned alongside of upper nine teeth 232. Adapted to cooperate with the teeth 232 are six feed pawls 234 (see also Fig. 22) positioned to the rear of the racks 218 and loosely mounted on a shaft 235 supported between forwardly extending arms of a U-shaped operating member 236. As shown in Fig. 15 the left-hand arm of member 236 is pivoted at 237 to the inside of the left-hand frame member 167. The right-hand arm of member 236 is secured to a shaft 238 (see Fig. 23) rotatably mounted in an extension of the side frame 166. Springs 239 (Fig. 15) tensioned between forward extensions of the arms on member 236 and the previously mentioned tie rod 223 serve to urge the member in a counter-clockwise direction as viewed in Fig. 15. Referring now to Figs. 9, 12, and 24, it will be seen that a forwardly extending arm 241 is fixed to the outer end of the shaft 238 and is connected to the upper end of a downwardly extending link 242. The lower end of the link 242 is connected to one end of a lever 243 (see also Figs. 1 and 17) pivoted at its mid point to the previously mentioned shaft 179 and bearing at its other end a roller adapted to follow the contour of a cam 244 fast on the shaft 2. As shown in Fig. 24 the cam 244 is formed with a single low spot or depression 245. It is evident that as long as the roller on lever 243 dwells on the high surface of the cam 244, the operating member 236 will remain inactive in the position shown in Fig. 15. Once each machine cycle, however, the roller will be permitted to drop into the low spot 245 under the tension of the springs 239, thereby causing the feed pawls 234 to move upwardly to advance one or more of the racks 218 in the following manner.
- 15 As shown in Fig. 15 the several pawls 234 are tensioned to move in a counter-clockwise direction about their pivot 235 by means of springs 246 tensioned between lower extensions of the pawls and the rear of the operating member 236. In order that the pawls may normally be disengaged from the racks 218, however, a plate 247, fastened to the frame member 167, is provided. 20 The pawls 234 normally rest with their respective noses bearing against the upper rear surface of the plate 247 and are adapted, when the member 236 is operated, to move off of the retaining plate to bear against the racks 218. The several pawls 234 are so arranged that as they move off of the plate 247 only the pawl of lowest order will be permitted to drop into engagement with the teeth 232 on its associated rack 218. The feed pawl of the second lowest order and all those to the left of this pawl are so positioned that they will be engaged by the previously mentioned plate 233 of the next lower order rack 218, and so be prevented from engaging their associated teeth 232. The lowest order rack 218 will thus be fed alone one step for each cycle of the machine as long as the sequential order of the record cards is unbroken. In order that the racks 218 may retain a correct decimal representation at all times it is evident that on the last or tenth step

of movement of the lowest order rack (assuming that this rack started at zero) the rack of next highest order must be fed one step at the same time and then the lowest order rack must be returned to zero to begin a new series of steps. Immediately after the ninth step of the lowest order rack 218, therefore, the feed pawl 234 of next higher order is permitted to drop off of its disabling plate 233 to engage a tooth 232 of its associated rack 218. Now upon the next step of movement of the member 236 both racks 218 of first and second lowest order will be simultaneously advanced one step. In order that the rack of lowest order may be returned to normal after its tenth step of movement a stud 248 is positioned on the right-hand side of the rack. The stud 248 cooperates with a forward extension of the associated detent pawl 227 to rock the pawl out of engaging position on the tenth step of movement of the rack. The upper rear surface of the detent pawl is formed with a notch 249 adapted to be engaged by one arm of a latch 251 pivoted on a shaft 252 loosely supported between the side frames 166 and 167. The latch 251 is urged in a clockwise direction (Fig. 15) by means of a spring 253 and will retain the pawl 227 in disabled position until it is itself disabled, when the rack has returned to zero, by a second stud 254 positioned on the upper end of the rack 218. Each rack 218 is provided with studs 248 and 254 and an associated latching lever 251 so that the above described carry operation, whereby a rack of higher order is fed one tooth space for every ten steps of the rack of next lower order, is effected throughout the entire set of six racks. It is evident, however, that inasmuch as the several racks 218 are originally set up according to a definite serial number they will be variably arranged when first operated by the member 236. Furthermore one or more of the racks may originally be positioned with its plate 224 opposite the nine pin 173. The feed pawl 234 of next higher order would thus be free to drop behind the plate 233 to advance its rack on the first operation of member 236. Therefore, a means is provided additional to the plates 233 for holding ineffective all of the pawls 234 to the left of the last operated pawl. Referring to Fig. 22 it will be seen that integral with each of the pawls 234 except the two of lowest order is a stud 255 projecting in a right-hand direction from the pawl and resting in or overlying a cut out portion 256 of the next lower order pawl. Thus it may be seen that pawl 234 of lowest order may rock into engagement with its rack 218 at any time; that the pawl of second lowest order is prevented from engaging its rack only by the plate 233; and that the remainder of the pawls are held ineffective by the studs 255 until released by the rocking of the next lower order pawl.

COMPARING OR FEELER MECHANISM

The mechanism previously noted for comparing the relative arrangement of the plates 224 and the pins 173 is also controlled from a cam on the main shaft 2 and operates once for every machine cycle except the cycle immediately following a total, at which time the plates 224 are limiting against extended pins 173 to set up a new number. As shown in Figs. 11 and 15 a link 257 is positioned directly in front of each of the plates 224. The upper end of each link 257 is pivotally connected to one end of an arm 258 loosely mounted on a shaft 259 fixed between the side frames 166 and 167. The lower end of each

link 257 is pivotally connected to one arm of a bell crank lever 261 loosely mounted on a sleeve 262 surmounting a shaft 263 supported for free rotation between the frames 166 and 167. The 5 sleeve 262 is supported independently of the shaft 263 by means of a pair of arms 264 dependent from a shaft 265 and a tie rod 266 both of which are fixed between the side frames of the unit. Each of the bell-crank levers 261 is urged to 10 move in a clockwise direction (Fig. 15) about its pivot 262 by means of a spring 267 tensioned between the forwardly extending arm of each lever and the tie rod 266. The levers 261 are normally held in the position shown in Fig. 15, 15 however, against the tension of springs 267 by means of a bail rod 268 overlying the upper forward edges of all of the levers 261 and supported between a pair of bell-crank levers 269 secured to the shaft 263. The bail rod 268 is caused to 20 remain in contact with the levers 261 by means of a pair of light springs 271 tensioned between upwardly extending arms of the levers 269 and studs 272 integral with the respective side frames 166 and 167 (see Fig. 11). Through a separate 25 means, soon to be described, the bail rod 268 is held locked in the position shown in Fig. 15. Once for each cycle of the machine, however, this locking means is disabled thereby, rendering the bail rod ineffective to prevent the levers 261 from rocking under tension of their springs 267. 30 It will be recalled that when the machine is in sequence, that is, when the record cards follow one another in sequential order, the operated pins 173 and their associated plates 224 are in exact alignment and the latter will be projected a short distance forward by the former. The 35 disabling of the above mentioned locking means for preventing the rocking of levers 261 occurs at a time when the plates 224 are extended under pressure of the pins 173. Each plate 224, when 40 extended, is positioned with its front edge contacting the rear edge of its associated link 257. Now, when the levers 261 are freed and attempt to move under tension of their springs 267 they 45 will be prevented from such movement by the extended plates 224. Before the pins 173 are returned to normal the bail rod 268 is again locked in retaining position and will not be released again until the following cycle. It is evident 50 that when the machine is out of sequence one or more of the pins 173 will be operated without causing a corresponding actuation of their associated plates 224. Thus, one or more of the links 257 will be permitted to move rearwardly to initiate the taking of a total in the following manner.

TOTAL INITIATION

As shown in Figs. 9, 11, 12, and 25 an arm 273 is loosely mounted on the shaft 263, near its 60 right-hand end, the arm 273 being connected at its free end to a downwardly extending link 274. The lower end of the link 274 is connected to the forward end of a lever 275 (see also Figs. 1 and 17) pivoted at its mid point to the shaft 179 65 and bearing at its opposite end a roller adapted to ride the periphery of a cam 276 secured to the shaft 2. As shown in Fig. 25, the cam 276 is formed with a single low spot 277 so that once for each cycle of the shaft 2, the lever 275 will rock briefly in a counter-clockwise direction to pull downward the link 274 and to rock the arm 273 a short distance in a clockwise direction about its pivot 263. Referring now to Fig. 12 it will be 70 seen that secured to the outer end of the shaft 75

263 is a finger-like arm 278 the rear end of which overlies a stud 279 integral with the arm 273. While the roller on lever 275 dwells upon the raised surface of the cam 276, the stud 279 will hold the finger 278, and thereby shaft 263 and bell-crank levers 269 in locked position, thereby preventing the rocking of levers 261. Once for each machine cycle, however, the pressure exerted by cam 276 is relieved, thereby releasing the finger 278 to permit it to rock in a clockwise direction (Fig. 12) or remain in its original position according to whether the machine is out of or in sequence. If in sequence, that is, if all of the plates 224 (Fig. 15) are extended, none of the links 257 will be permitted to move rearwardly and the shaft 263 will not be rocked. If out of sequence, one or more of the links 257 will move rearwardly, thereby causing the shaft 263 to rock in a clockwise direction, through levers 261 and bail rod 268. As shown in Figs. 11 and 13 there is secured to the left-hand end of the shaft 263 bell-crank 281, the lower end of which is connected to the previously mentioned link 127 connected at its lower end to the two-armed lever 126 (see Fig. 8). As previously mentioned anything which pulls the link 127 upward to rock the lever 126 will institute a total taking operation. It is evident, therefore, that a counter-clockwise rocking motion of the shaft 263 (as viewed in Fig. 13) will cause a total taking operation to be performed in the machine.

Also provided in the present machine is an additional blocking means for preventing an operation of the shaft 263 when the machine is not being used for the verification of sequentially numbered record cards. As shown in Figs. 11 and 13 there is secured to the left-hand end of the previously mentioned shaft 263 an upstanding arm 282 to the upper end of which is connected a link 283 connected at its opposite end to one arm of a bell-crank lever 284. The lever 284 is pivoted to a stud 285 integral with the frame piece 167 and its other arm bears a stud 286 adapted to cooperate with a shoulder formed in the upper end of the above mentioned bell-crank 281. With the above described linkage positioned as shown in Fig. 13 it is evident that the stud 286 will prevent the rocking of shaft 263. A spring 287 tensioned between the lever 284 and a stud on the frame 167 urges the lever 284 into blocking position. In normal machine operation, however, the arm 282 is adapted to be pressed forwardly, to disable the lever 284, through the medium of the special pin 165a controlled by the special translator wire 42 as shown in Figs. 6 and 15. The wire 42 will remain continually effective as long as the special control hole appears in the record cards.

As previously noted a means is also provided for rendering the comparing mechanism ineffective to initiate the taking of a total during the machine cycle immediately following a total since it is during this cycle that a new number is set up on the racks 218. As shown in Figs. 11 and 12 an arm 288 is secured to the shaft 263 near its right-hand end. The arm 288 extends downwardly from the shaft 263 and has its lower end positioned slightly above and to the rear of a lever 289 fast on a shaft 291 which shaft is pivotally supported between the extreme forward ends of the frames 166 and 167. The lever 289 and its shaft 291 are adapted to be rocked upward in a counter-clockwise direction (Fig. 12), through means soon to be described, during the last portion of the total cycle and the first por-

tion of the next following cycle. With the lever 289 in its elevated position the arm 288 limits against the rear edge of the lever and when rack comparing occurs during this cycle the shaft 263 will be prevented from rocking. As pointed out in the timing diagram to follow, the rack comparing operation takes place during the early part of each cycle and therefore occurs at a time when the lever 289 is in elevated position.

10

NEW NUMBER SET-UP

As shown in Figs. 9, 11, and 12 there is secured to the right-hand end of the shaft 291 a rearwardly extending arm 292 bearing a stud 293 at its outer end. The stud 293 passes through a slot 294 cut in a plate 295 fastened to the upper end of a downwardly extending link 296. As shown also in Figs. 1, 17, and 26 the link 296 is secured to a second link 297 connected at its lower end to a lever 298 pivoted to the previously mentioned shaft 179. Mounted on the opposite end of the lever 298 is a roller adapted to follow the contour of a cam 299 fast on the shaft 2. A spring 301, tensioned between the plate 295 and a stud on the frame 166, serves to maintain the roller on lever 298 in contact with its cam 299. The cam 299 is adapted to move the lever 298 positively in a reciprocable rocking motion once for each cycle of the shaft 2, thereby imparting reciprocable vertical movement to the links 297, 296, and the plate 295. As shown in Fig. 12, the slot 294 formed in the plate 295 is shaped somewhat in the form of an inverted L, that is, the slot extends forwardly at its upper end to form a shoulder 302 whereas its lower end is cut only to sufficient width to enable the stud 293 to be passed therethrough. During total taking operations, however, mechanism soon to be described is provided for shifting the plate 295 rearwardly in order that the stud 293 may be engaged by the shoulder 302 formed in slot 294. It is evident that the shifting of plate 295 may occur only when the plate is in its extreme lowest position. Then, it will be seen that as the plate 295 begins its upward travel, the arm 292 and the shaft 291, to which the arm is secured, will be rocked in a counter-clockwise direction, as viewed in Fig. 12, until the plate reaches its extreme elevated position. Referring now to Figs. 11 and 15 there is secured to the shaft 291 a pair of arms 303 positioned just inside the respective frame pieces 166 and 167. The arms 303 extend rearwardly through the comparing unit and support between their far ends a bail rod 304 which underlies all six of the racks 218. Counter-clockwise movement of the shaft 291 (Fig. 15) will, therefore, cause the elevation of the racks 218 to their highest raised position which is one tooth space above the number nine pins 173. Near the end of this upward movement the detent pawls 227 are disabled by the studs 248 on the racks 218 so that as the shaft 291 returns to normal the racks may follow the bail rod 304 until they limit against extended pins 173 to set up the new number. As previously described, the detent pawls 227 are adapted to be held in disabled position by the retaining latches 251. It is evident that all of the latches 251 will not be disabled through the medium of studs 254, since, when setting up a new number, some of the racks 218 will not return to zero. Therefore, a positive actuating means is provided for disabling the retaining latches 251 after the descent of the bail rod 304.

As shown in Fig. 11 and in dot dash outline

in Fig. 15 the rearmost end of the right-hand arm 303 normally bears against the forward edge of a plate 305 pivoted to an arm 306 secured to a stud shaft 307 pivotally supported by the frame plate 166. The plate 305 is tensioned to move in a counter-clockwise direction, about its pivot on arm 306, by means of a spring 308 tensioned between a rearward extension of the plate and a stud on the arm. The plate 305 is further connected to the arm 306 by means of a pin and slot arrangement, the spring 308 serving to maintain the rear edge of a slot in plate 305 in contact with a pin on the arm 306. Thus, it will be seen that as the arms 303 begin to move upwardly the plate 305 will be cammed rearwardly, against the tension of its spring 308 and that as the arms continue their upward travel the pressure exerted on plate 305 will be relieved and the plate will snap back to its original position. Then on the return stroke of the arms 303, and shortly before they are completely restored to normal, the forward end of the right-hand arm 303 will contact the upper edge of the plate 305 to cam the plate 305, the arm 306 and the stud shaft 307, to which the arm is secured, all in a counter-clockwise direction (Fig. 15). Continued downward movement of the arms 303 will release the plate 305 and permit the assembly of which it is a part to return to normal. Referring to Figs. 11, 12 there is secured to the right-hand end of the shaft 307 a lever 309. As viewed therein, counter-clockwise motion of the shaft 307 is performed against the tension of a spring 311 and serves to lower a link 312 connecting the lever 309 and an arm 313 fast on the shaft 252, on which the retaining latches 251 are pivoted. The lowering of link 312 serves to rock the shaft 252 in a counter-clockwise direction. As shown in Figs. 11, and 15 there is secured to the shaft 252 a pair of arms 314 positioned just inside the respective frame plates 166 and 167. Supported between the pair of arms 314 is a bail rod 315 positioned just to the rear of the retaining latches 251. Counter-clockwise movement of the shaft 252, therefore, will be imparted through the arms 314 and bail rod 315 to the latches 251 to disable the latches and permit the detent pawls 227 to engage their respective racks 218.

Returning now to the means for shifting the plate 295 during total strokes it will be seen (Fig. 12) that the plate is formed with an upwardly extending arm to which is connected a link 316 resiliently connected at its other end to the lower end of an arm 317 secured to the right-hand end of a shaft 318. The shaft 318 extends through the plates 166 and 167 (see Figs. 11 and 23) and its left-hand end is coupled to a shaft 319 loosely supported at its opposite end, in a manner noted below, by the previously mentioned collar 121a (see Fig. 5A). As shown in Figs. 5, 5A, 8 and 36 the previously mentioned lever 116 which is adapted to operate the total link 118, is also connected to another link 321 connected at its upper end to an arm 322 fast on the extreme left-hand end of shaft 319. As shown in Fig. 5A the hub on arm 322 is pinned to the shaft 319 and also rests on the outer end of the stud 121a thereby providing a support for the shaft 319. The operation of lever 116, therefore, will not only pull the total link 118 to cause a total to be taken from the accumulators, but will also rock the shaft 319 in a counter-clockwise direction (Fig. 5) which, through the shaft 318, arm 317 and the link

316, will shift the plate 295 rearwardly to condition the machine for a new number set up on the racks 218. The shaft 318 is rocked early in the total cycle but the link 316 may not shift the plate 295 until the plate reaches its extreme lowered position. It is understood that the shaft 318 remains rocked for the duration of the total cycle.

MEANS FOR MANUALLY SETTING RACKS 218

As shown in Figs. 11 and 15 the previously mentioned arms 220, one of which is secured to the upper end of each rack 218, extend downwardly and forwardly in front of the comparing unit and are guided in a slotted bracket 230 secured to the frames 166 and 167. The forward ends of the arms 220 extend through the guide plate 230 and are easily accessible to permit manual control in order that the racks may be pre-set to any desired setting, the bracket 230 being suitably inscribed with six columns of figures from zero to nine. Thus, if for any reason the machine is stopped while sensing in sequence and the racks 218 disarranged, the racks may be set manually to their correct position before the machine is again started. The above manual control also makes it possible, when beginning a run of cards, to present the racks in accordance with the serial number of the first card to be sensed thereby rendering unnecessary and preventing a total taking operation immediately after the machine is started.

NAUGHT BLOCK DISABLING MEANS

As mentioned earlier in the description the naught block 132, associated with the "first number" unit (see Fig. 3), is adapted to remain elevated during every machine cycle except the idle cycle preceding a total, the total cycle itself and the cycle immediately following a total. Referring now to Figs. 4 and 9 it will be recalled that the block 132 is normally held upward by a latch 151 engaging a finger 148 on the translator shaft 136. A spring 152 tends to hold the latch 151 in engaging position while a forwardly extending link 153 is connected to the latch 151 in order that the latch may be disabled during the period stated above. The link 153 (Fig. 12) is loosely supported near its forward end by the frame of the translator and has its extreme front end bent over in the form of a lug 153A. Positioned directly in front of the lug 153A are the respective upper and lower ends of a pair of arms 323 and 324 secured to the respective shafts 208 and 318. As shown in Fig. 12 the arm 323 on the shaft 208 is bearing against the lug 153A, whereas the arm 324 on the shaft 318 is positioned slightly to the front of the lug. It will be recalled, however, that during sequential verification work the shaft 208 is normally held rocked in a counter-clockwise direction by means of the special control pin 165. Thus, the arm 323 is normally held in approximately the same position as arm 324 while the link 153 and its lug 153A are caused to bear against both arms by means of the spring 152. While the link 153 occupies the above position, the latch 151 is free to engage the arm 148 to hold the naught block 132 elevated. If, however, the link 153 is caused to move rearwardly by either arm 323 or 324 the result will be to disable the latch 151 thereby permitting the block 132 to drop to ineffective position. The arm 323 is permitted to operate the link 153 at the beginning of the above mentioned idle cycle due to the retraction of the locking slides 29 which cause all

of the wires in the translator to drop from elevated position. Then, at the beginning of the total cycle the arm 324 is rocked rearwardly to retain the link 153 in disabled position during the total cycle. This is necessary due to the fact that the translator wires will rise and fall briefly during the total cycle so that, unless the arm 324 is provided, the latch 151 may effectively engage the arm 148 for a short time during this cycle.

DISABLING MEANS FOR COMPARING UNIT

An important feature of the present machine is the ease with which the sequence verifying mechanism may be disabled in order to permit the machine to be used for regular adding and listing work. In the present machine the comparing mechanism may be completely disabled merely by replacing the translator described herein with one of a different construction. As shown in Figs. 6 and 9 there is secured to the right-hand front surface of the present translator a forwardly extending bracket 327 adapted to bear against and hold rocked, a lever 328 pivoted at its mid-point to the previously mentioned shaft 175. The lower end of the lever 328 bears a stud 329 which extends through a slot cut in a lever 331 (as is best shown in Fig. 12) secured to a sleeve loosely mounted on a stud 332 integral with the frame member 166. A spring 333 tensioned between the stud 329 and a stud on the frame 166 tends to urge the lever 328 in a clockwise direction and serves to maintain the lever in contact with the bracket 327. Also secured to the sleeve, surmounting stud 332, is an arm 334 projecting forwardly and rearwardly from its pivot point. With the lever 331 and arm 334 positioned as shown in Figs. 9 and 12 the comparing and total initiating operations may proceed in the manner previously described. If, however, the translator is removed, the pressure exerted on lever 328 by bracket 327 will be relieved and the lever will pivot in a clockwise direction (Fig. 12) under the influence of spring 333. Clockwise motion of the lever 328 serves to rotate the assembly comprising lever 331 and arm 334 in a counter-clockwise direction until the upper end of the arm 334 limits against a stud 335 on the previously mentioned arm 176 associated with the pin box reciprocating mechanism. The next time the arm 176 is raised to move the pin box 169 rearwardly, the assembly 131 and 134 continues its counter-clockwise motion until it occupies the position shown in Fig. 27 with the uppermost edge of arm 334 positioned beneath the stud 335. As further illustrated in Fig. 27, the lever 331 has a stud 336 formed on its forward end, adapted, when the lever is rocked, to lie directly in the rear of the link 296, thereby preventing the link and its associated plate 295 from being shifted rearwardly during total strokes. Positioned on the forward end of the arm 334 is a stud 337 adapted to move beneath a shoulder plate 338 (see Fig. 9) secured to the link 242 in order to prevent the operation of the pawl feeding mechanism associated with this link. Thus, unless a translator bearing a projection 327 is in the machine, the means for reciprocating the pin box 169, the means for elevating the racks 218 on the first cycle following a total, and the means for individually feeding the racks 218, will all be disabled.

DESIGNATION AND LINE-SPACE-MECHANISM

In the present machine it is desired to so regulate the printing mechanism that printing may be effected only during total taking cycles. In

order that each group of sequentially numbered cards may be recorded on one line of the report sheet, line space mechanism is provided which may be set to operate also only on totals. The designation and line space mechanisms used herein for the above purpose are old and well known in the Powers machine and have been described in a previous Patent No. 2,255,670, issued September 9, 1941.

10

45-COLUMN MODIFICATION

The comparing unit disclosed herein has been described as operating in conjunction with a ninety-column Powers type tabulator. The unit 15 may, however, be mounted on a forty-five-column machine without a change in the unit itself. The decoding pin box 169, as shown in Fig. 14, must, however, be replaced by one of a different construction, preferably of the type shown in Figs. 28, 29, and 30. As shown therein, the pins 173 are arranged in six columns of ten pins to the column and operate to set up the racks 218 in the same manner as the pins in the ninety-column box. The pins 173 are themselves operated by pins 165 (Fig. 10) identical in number and arrangement to the pins 173. It is understood that in a forty-five-column machine the translator used therein will have ten wires to a column instead of the six required for ninety-column work. As shown in Fig. 28, the extrusions on the odd numbered pins 173 extend in one direction while the extrusions on the even numbered pins extend in the opposite direction. Co-operating with each set of extrusions are identical locking slides 329 adapted to retain their associated pins 173 in extended position. Only one pin 173 per column will be operated at one time.

40

Referring now to Figs. 32 and 33, the timing of certain operating mechanisms of the machine is diagrammatically shown therein with respect to the movement of the main cam shafts 2 and 3. The machine has been timed through four complete and successive machine cycles. These cycles are illustrated in the order in which they occur and are as follows: Add, or normal, Idle, Total, and Normal. The idle cycle is the usual space or blank stroke which always precedes a total.

45

ADD CYCLE

Considering first the "add" cycle (Fig. 32) it will be seen that the record card begins its travel 45 out of the storage magazine at 60° of rotation of the drive shaft 2 and reaches full reading position at 226° , at which time it is limiting against the card stop 18 (Fig. 5). The card remains in reading position for the duration of the cycle. The card stop 18 is normally closed and begins to open at $113\frac{1}{2}^\circ$ of this cycle to permit the ejection of the card sensed on the preceding cycle. The stop is fully open at $131\frac{1}{2}^\circ$ and remains so until $193\frac{1}{2}^\circ$, when it starts to close. The card stop is fully closed at $211\frac{1}{2}^\circ$. The retraction of the locking slides 29 is normally a short intermittent operation beginning at 334° and ending at 360° . The lower pin box 21 (Fig. 2) is reciprocated vertically once for each cycle of the machine. The box is normally up, and under the control of eccentric disc 22 will descend until 180° at which time it immediately starts up again, reaching its extreme elevated position at 360° . The translator wires 37 and 43 reach their operative elevated

50

55

60

65

70

75

75

position at 340° of one cycle and normally begin to descend at about 334° of the next cycle. The sector rock shaft 72 (Fig. 4) moves in a reciprocal rocking motion under the control of the cam 68 on the shaft 3. During the first 180° of movement of the shaft 3, the rock shaft 72 moves in a clockwise direction (Fig. 4) to release the sectors 48 and 51 and to operate the hammer release shaft 77. During the second 180° of movement of shaft 3, the shaft 72 rocks in the opposite direction to permit the restoration of the sectors and the hammer release mechanism to normal. The sectors reach their zero printing position at 70° of the cycle, at which time they may be prevented from further movement by upraised zero stops 49 (Fig. 3) or may continue to move forward if their associated zero stops have been depressed.

The decoding pin box 169 (Figs. 12, 14, and 16) is at its extreme rearward position, against the translator pins 165, at 0°. The box starts forward at 0° under the control of its cam 182 and reaches the racks 218 at 20° where it dwells until 340°. At 340° the pin box starts rearwardly, reaching the translator at 355°, to enable its pins 173 to be operated by the extended translator pins 165. The locking slides 186, 192, and 194 of the decoding pin box 169 are retracted once for each machine cycle. Under the control of cam 215 (Fig. 21) the slides begin to retract at 226° and are fully retracted at 246°. They then dwell in retracted position until 345°, when they start to restore to normal. At 360° the slides 186, 192, and 194 are in normal locking position. The advancement of racks 218 by operating member 236 (Fig. 24), through the medium of cam 244, begins at 260° of each cycle and ends at 320°, the rack being advanced one tooth between 286° and 292°. The comparing mechanism for sensing the relative arrangement of the plates 224 and pins 183 operates under the control of cam 276 (Fig. 25). The sensing operation begins at 22°, the racks are fully sensed at 46° and the mechanism restored to normal at 72°. It will be noted that in the "add" cycle illustrated herein the machine is "in sequence," that is, the parallel links 257 are prevented from moving rearwardly by the pressure of extended plates 224 even though they are released for operation by the cam 276. The comparing mechanism remains in its normal position, therefore, and the cam 276 may be considered to be ineffective. After the comparing operation and at about 55° of the cycle, the gear sectors 515 (Fig. 37) begin to move from engagement with their actuating racks under control of the cam 588. The sectors begin to reengage their racks at about 165° of the cycle and are fully engaged at 185°. The naught block 132 (Fig. 3) is up throughout a normal "add" cycle.

IDLE CYCLE

Considering now the "idle" cycle, it will be remembered that the comparing operation begins at 22° of the cycle. Assume now that on the cycle immediately following the one described above the plates 224 and pins 173 are not identically arranged. Thus, at about 32° of this cycle a total taking will be initiated and very shortly thereafter, the total control unit is fed one step thereby instituting an idle machine cycle. The time of advancement of the total control unit is not shown herein, but occurs at approximately 54° which is later than the standard practice in tabulators of the Powers type. As described in

the above mentioned Ferry Patent No. 2,185,841, as soon as the machine enters into the "idle" cycle, the card feed mechanism is disabled, the card stop is held in closed position and the retract bail is operated at 85° to release the locked intermediate pins 26 and the translator wires 31 and 43. Thus, for the duration of the "idle" cycle the card which initiated the taking of the total is held in the sensing chamber in reading position and at about 60° all of the translator wires will start to drop down out of operating position. At 110° the wires are completely down and will remain so until 290° when they again begin to rise as the lower pin box moves towards its elevated position. At 340° the wires are entirely up again but inasmuch as the locking slides 29 are still retracted the wires will descend with the lower pin box at 20° of the next cycle. As the translator wires descend shortly after the start of the "idle" cycle, the retaining means for holding the naught block 132 elevated is disabled so that from 65° to 75° of this cycle the block descends to normal position. The block remains down until 320° of this cycle when it starts upward again under the control of cam 138. At 350° the block is entirely up but returns immediately to lowered position since its latch 151 is at this time disabled by link 153. The zero stops 49 are all elevated during the "idle" cycle, thereby retaining the sectors 48 and 51 at zero. The operation of the total control unit during this cycle will enable the cam 602 thereof (Fig. 37) to render the sector engaging and disengaging cam 588 ineffective whereby the sectors 515 will remain engaged with their racks throughout the entire cycle.

TOTAL CYCLE

(Fig. 33)

The mechanism, previously mentioned for retaining the card in reading position and for holding the locking slides 29 retracted throughout the "idle" cycle, is also effective throughout a major portion of the "total" cycle. The card stop is held closed for the duration of the "total" cycle while the locking slides 29 are permitted to resume their engaging position at 350° of this cycle to permit accumulation of the first card of a new group during the following cycle. The translator wires, as mentioned above, descend with the lower pin box at 20° of the total cycle. At 290° of the cycle they start up again and shortly after reaching operative position are locked therein by the slides 29. The decoding pin box 169 operates near the end of the "total" cycle to receive the set-up of the new number from the pins 165. Advancement of racks 218 by cam 244 takes place during both "idle" and "total" strokes, but serves no purpose since the machine is going through a total taking operation. A comparing operation also takes place during the "total" cycle, and the mechanism attempts to trip a second total. However, this motion is ineffective since at the time this operation takes place, the position of the total feed cam 102 (Fig. 7) is such as to prevent the descent of the push rod 184 so that the ratchet wheel 109 may not be operated a second time. The naught block 132 remains down throughout most of the total cycle. Late in the cycle it moves upward under control of the cam 138 but immediately descends and does not affect the movement of the sectors 48 and 51. The T link 118 (Figs. 5 and 8) is pulled by the cam 115 at 345° of the "idle" cycle and remains in operated position

until 350° of the total cycle. The racks 218 begin to move upward under the actuation of the bail rod 304 (Fig. 26) at 300° of the "total" cycle and reach their highest elevated position at 350° at which point they dwell for a short period. The sectors 575 remain in engagement with their racks during the cycle and control the printing of the "last No." in the described manner.

NORMAL CYCLE

At the end of the "total" cycle all of the disabling mechanisms controlled by the automatic total control unit are normalized and resume operations under their regular controls. The card which tripped the total was positively sensed at the end of the "total" cycle and this card begins to leave the sensing chamber at 124° of the "normal" cycle. The translator wires are up throughout the cycle and the decoding pin box reaches its forward position at 20° of the "normal" cycle. At approximately 10° of this cycle, the rack 218 begins to descend and from that point until 235° of the cycle, the several racks stop off at the set-up pins 173. In a manner previously described, the comparing mechanism is prevented from operating during this cycle. The naught block 132 remains down during the major portion of this cycle in order that the new number may be accumulated in the "first No." unit. Near the end of this cycle the block is again raised by the cam 138 and is held elevated by the latch 151. The rack feeding and slide retract mechanisms operate effectively during this cycle to condition the unit for the second cycle of the new group.

While there is above described but one embodiment of the invention, it is possible to produce still other embodiments without departure from the inventive concept above disclosed, and it is, therefore, desired that only such limitations shall be imposed on the appended claims as are stated therein.

What I claim as new, and desire to secure by Letters Patent, is:

1. In a machine of the class described through which is passed a succession of record cards having consecutive serial numbers punched therein, the combination of record sensing means, means for feeding the cards successively to said sensing means, a total taking control mechanism, means controlled by said sensing means for detecting a break in the consecutive order of said serial numbers, a reciprocable cyclically operated actuating rack controlled in its reciprocating movement by said sensing means, an item storage element having a normal zero position, cyclically operated means for engaging the storage element with the actuating rack during its normal rearward movement and disengaging it therefrom at the beginning of its following normal forward movement, means for restoring the storage element to its zero position as soon as it is disengaged from its actuating rack, means controlled by the detecting means to initiate an operation of the total taking control mechanism when a card number is not in consecutive order, and means controlled by the total taking control mechanism, when set into operation, to temporarily disable the engaging and disengaging means to cause the storage element to be retained in engagement with the actuating rack during the forward stroke of the total cycle initiated by the total taking control mechanism, whereby the rack on its forward stroke is set to represent the number stored in said element.

2. In a machine of the class described through which is passed a succession of record cards with consecutive serial numbers punched therein and having record sensing means and a total taking control mechanism, the combination of an accumulator, item storage elements having zero positions, reciprocable actuating elements common to the storage elements and the accumulator, means under the control of the record sensing means to differentially set said actuating elements, spring means between said item storage elements and fixed points in the machine whereby the storage elements are returned to zero position when disengaged from their actuating elements, a timed mechanism for causing the engagement and disengagement of said accumulator and its actuator, said timed mechanism being normally conditioned for non-adding, a second timed mechanism for causing the engagement and disengagement of the item storage elements and their actuators, said second timed mechanism being adapted to control its storage elements for temporarily storing each serial number, means controlled by said sensing means for detecting a break in the consecutive order of said serial numbers, means operated by the detecting means when the numbers do not follow in consecutive order to initiate the operation of the total taking control mechanism, means operated by said total taking control mechanism to alter the cyclical operation of the first timed mechanism to condition the accumulator for adding operations, and means also operated by the total taking control mechanism for altering the cyclical operation of the second timed mechanism for causing the storage elements to be retained in engagement with their actuators during the first stroke of a total cycle whereby the number then in the storage elements will be transferred to the accumulator.
3. In a machine of the class described through which is passed a succession of record cards with consecutive serial numbers punched therein and having record sensing means and a total taking control mechanism, the combination of an accumulator, item storage elements having zero positions, reciprocable actuating elements common to the storage elements and the accumulator, means under the control of the record sensing means to differentially set said actuating elements, spring means between said item storage elements and fixed points in the machine whereby the storage elements are returned to zero position when disengaged from their actuating elements, a timed mechanism for causing the engagement and disengagement of said accumulator and its actuator, said timed mechanism being normally conditioned for non-adding, a second timed mechanism for causing the engagement and disengagement of the item storage elements and their actuators, said second timed mechanism being adapted to control its storage elements for temporarily storing each serial number, means controlled by said sensing means for detecting a break in the consecutive order of said serial numbers, means operated by the detecting means when the numbers do not follow in consecutive order to initiate the operation of the total taking control mechanism, means operated by said total taking control mechanism to alter the cyclical operation of the first timed mechanism to condition the accumulator for adding operations, and means also operated by the total taking control mechanism for altering the cyclical operation of the second timed mechanism.

anism for causing the storage elements to be retained in engagement with their actuators during the first stroke of a total cycle whereby the number then in the storage elements will be transferred to the accumulator, means controlled by said record sensing means to initiate a grand total operation of said total taking control mechanism, means operated by the total taking control mechanism during a grand total operation for controlling the second timed mechanism to effect a disengagement of the storage elements from their racks during the forward stroke of the grand total cycle, and means also operated by the total taking control mechanism during a grand total operation for controlling the first timed mechanism to cause the accumulator to go through a total taking operation, whereby the sum of the amounts transferred from the storage elements to said accumulator may be recorded.

4. In a machine of the class described through which is passed a succession of record cards with consecutive serial numbers punched therein and having record sensing means and total taking control mechanism, the combination of an item storing device comprising a movable sector having a normal zero position, a differentially set-

table reciprocable rack adapted to engage and move said sector and movable in a forward and return stroke for each machine cycle, means controlled by the sensing means for differentially setting said rack, timed mechanism connected to said sector and cyclically operated to cause engagement and disengagement of the sector and the rack, the normal cyclical operation of each timed mechanism causing disengagement of the rack and sector on the forward stroke of the rack and engagement on the return stroke of the rack, a spring connected to the sector for moving it to normal position when disengaged from the rack, means controlled by the record sensing means for detecting a break in the consecutive order of said serial numbers, means controlled by said detecting means to initiate an operation of the total taking control mechanism when a card having a number out of order is sensed, and means operated by the total taking control mechanism, when operated, to control said timed mechanism to retain the sector and rack in engagement thereafter on the forward movement of the rack whereby the rack on said forward stroke is set to represent the number stored in the sector.

JOSEPH M. McDONNELL.

Certificate of Correction

Patent No. 2,288,823

July 7, 1942

JOSEPH M. McDONNELL

It is hereby certified that error appears in the printed specification of the above numbered patent requiring correction as follows:

Page 1, second column, line 43, for the word "providing" read *proving*; page 22, second column, line 8, strike out "each";

and that the said Letters Patent should be read as corrected above, so that the same may conform to the record of the case in the Patent Office.

Signed and sealed this 7th day of November, A. D. 1950.

[SEAL]

THOMAS F. MURPHY,
Assistant Commissioner of Patents.
